AERODYNAMIC LIFTING DEVICE AND METHOD OF LIFTING

This application is a continuation of my copending application U.S. Ser. No. 72,348, filed Nov. 29, 1960 and now abandoned, and is a continuation-in-part of my copending application U.S. Ser. No. 20,799, filed Apr. 5, 1960 and now abandoned, which last mentioned application in turn is a continuation-in-part of my copending application U.S. Ser. No. 14,782 filed Mar. 14, 1960 and now abandoned.

This invention relates to an aerodynamic lifting device and method of lifting which may be used in a plurality of ways, for example, as a toy for amusement, a toy for educational purposes, an amusement device for use in amusement parks and the like, an educational device for use in lectures on aerodynamics and the like, a transportation device on which a load may be placed with the device being pulled, a transportation device which may self propelled, a transportation device which may be used amphibiously over land and water, and as a device having a relatively rigid support member from which a relatively flexible curtain is supported, which curtain aids in enclosing an air cushion for lifting the relatively rigid support member a substantial distance above the ground surface (the words "ground surface" or "ground" being used in a broad sense to include both land and water and the like). These uses are by way of example only, and are intended to show only some of the many uses to which the invention may be applied.

Accordingly, several forms of the invention are illustrated in the drawings diagrammatically in a manner to enable those skilled in the art to make aerodynamic devices according to this invention.

Some of the forms illustrated are shown without self-propelling or guiding means and may be used stationarily or may be pulled or pushed along, as desired. These same forms, and other forms illustrated, may be provided with self-propelling and/or guiding means. These self-propelling and/or guiding means may be in the forms of weights, jets, valves, fans, and the like. All of these self-propelling and/or guiding means may all be placed on a single device and may be used simultaneously, sequentially, or singly. They may also be used together to modify each other and may be used sequentially where various conditions of travel are encountered. They may be used, for example, at a lecture, where the efficacy and relationship of each particular control device may be illustrated as the lecture proceeds. These various self-propelling means may be used together, each to modify each other, under certain conditions of propulsion or travel. These self-propelling and/or guiding means may all be placed on a toy to enhance the attractiveness and interest therein and to supply a variety of uses for the toy, or any one or more of these means may be used in a less number than the particular illustration, as desired. Any or all of these self-propelling and/or guiding means may be used in all embodiments where they are applicable.

The self-propelling and/or guiding means may be manually set, for example, on a toy or lecture educational device to produce the propulsion and guidance desired. When manually settable they may be provided with sufficient frictional resistance to displacement to remain in the manually set position. These propulsion and/or guidance means may be also actuated to the desired condition or position by actuating means in which the manipulator, pedal, handle, or guiding wheel, and the like, may be relatively distant from the self-propelled and/or guiding means.

At the present development of industry, the art of actuating a device, such as a jet, vane, valve, blower, and the like, from a distant control member such as by a lever, switch, key, wheel, and the like, has attained the status of a well-developed industry. Such industry can now provide controllers of this type, which easily and efficiently produce such motions as the turning of a vane, the moving of a valve, the turning of the effective direction of any device, such as a blower or electric fan or the like, the moving of a weight, and other such means. This industry can provide means to move these devices propor-

tionately to the movement of the controlling switch, lever, wheel, or the like. For example, small motors are available which are controlled by suitable switches having suitable levers and the like. The motors are reversible, if desired, and are provided with actuating levers, gears, such as worm gears, and other well-known movements to produce the desired motion of the desired device. For example, windows on automobiles are now moved upward and downward by the mere corresponding motion of an upward or downward movement of a small lever on a switch, or the like. The movement of the window has been produced hydraulically, as well as by small motors. Vanes on airplanes and many other devices on airplanes are controlled by proportionally movable controllers at the pilot's cabin. Small motors, and the gearing, and slip clutches, etc., actuated thereby, are made and sold by many manufacturers, such as General Motors Corporation of Detroit, Michigan, Globe Industries, Inc., of Dayton, Ohio, and many others. These and other manufacturers produce "actuators" capable of proportionally actuating a device from a relatively long distance proportionally to the movement of the control member adjacent the user and particularly controllers for automobile windows and all of the necessarily movable parts on an airplane and the like. The very small motors which they provide, by way of example, may be energized from a small battery which may be chargeable during operation of the vehicle or the like or during its idle periods, as desired. Accordingly, applicant has illustrated only the novel correlation of the propulsion and/or guiding members, in many instances, since the "actuator system" has now attained a well-known and conventional status of its own and hence can be provided or purchased, need not be specifically illustrated in detail.

However, merely by way of example, some of such actuator systems of distant control have been illustrated to show typical systems for use in controlling some of the vanes, weights, and the like, which are shown herein. It is to be understood that such actuator systems, and similar systems, both mechanical and/or electrical, may be used to actuate any of the controls herein disclosed. Additionally, it is understood that any of the controls illustrated on any one embodiment may be used in other embodiments, as desired, and every conceivable permutation is not specifically shown, in the interest of avoiding superfluous illustrations.

Where the aerodynamic lifting device is intended for use in transporting a load, such as a passenger load and the like, over water, suitable pontoons may be incorporated in any of the embodiments disclosed. Such pontoons are illustrated and described hereinafter as applied to a typical embodiment, but are applicable to all embodiments. Such application of pontoons is not repeated to avoid superfluous illustrations.

This invention relates to a vehicle, craft, or glider which lifts itself from a "ground" surface by a cushion of air which is maintained at suprathermospheric air pressure. The air cushion produces a lifting action as it presses upward against the under surfaces of the supporting member to overcome the downward pressure of atmospheric air on the upper surfaces of such supporting member. The air cushion is surrounded by a substantially air impervious cylindraceous or columnar side wall construction which prevents any substantial uncontrolled escape of the suprathermospheric air of the air cushion except at a relatively narrow space under the lower edge of the columnar side wall construction. Only a small amount of power is required to operate air moving means which blows air from the surrounding atmosphere into the air cushion to replace the air which escapes under said lower edge of the columnar construction.

The narrow space between the lower edge of the columnar construction and the "ground" surface permits the craft to move or be moved sidewise over the "ground" surface. A relatively high, thin, flexible, air impervious curtain forms a substantial portion of the lower part of the columnar construction. Such curtain can extend upwardly from the lower edge of the columnar construction for a relatively great distance to permit such curtain to flex and pass over relatively large ob-

structions, such as large stones, etc., without harm to the relatively rigid upper supporting member. The lower space within the curtain is unobstructed by any rigid parts of the craft during normal operation, so the craft may pass over such large stones, etc., without damaging or jarring impact. In this manner the craft may move over a relatively rough "ground" surface and still maintain a relatively narrow escape space at the bottom of the curtain.

The flexible curtain also permits the craft to be tilted for control purposes, and/or to compensate for hills or slopes to maintain the supporting member substantially level.

The vehicle, craft or glider may be used to transport any desired loads, both animate or inanimate, over the surfaces of land, marshes, or open water, and such surfaces are intended to come under the convenient description of "ground" surface.

Such vehicles, crafts, or gliders may be used for amusement purposes in amusement parks, as a toy at home, or elsewhere, or they may be used for practical purposes such as for the transportation of persons or things over relatively long distances over land or water. They may be used singly or in joint formation for various purposes. They may be used amphibiously and interchangeably over land, marsh, or water surfaces.

In some embodiments herein disclosed, all of the parts of the craft are distributed to produce a substantially equally balanced weight condition throughout the craft. The weights of the parts normally are distributed about a vertical axis to provide a balanced condition without tilting action.

A relatively thin flexible curtain encloses at least a part of the air cushion in a manner to prevent undue loss of the air within the cushion. This thin flexible curtain automatically maintains itself in upright position notwithstanding that its material is practically non-self-supporting edgewise. The curtain is so shaped that it easily glides over relatively high obstructing objects and relatively rough "ground" surface in a surprising manner.

The thin and flexible curtain maintains the solid or unyielding parts of the supporting member at a relatively great height above the "ground" surface so that such solid or unyielding parts pass over relatively high objects without impact, while the thin and flexible curtain yields and glides over such high objects without jarring effects on the solid or unyielding parts of the supporting member.

To this end, a supporting member, during normal operation, is supported by an air cushion at superatmospheric pressure. The lower part, or more, of the air cushion is surrounded and is retained by a thin, flexible, hollow, columnar curtain which has its lower edge slightly spaced from a "ground" surface, during normal operation, to permit restrained escape of air from said cushion between the lower edge of the curtain and the "ground" surface. Air moving means withdraws air from the surrounding atmosphere and discharges said air at superatmospheric pressure into said air cushion to maintain the air in the cushion at superatmospheric pressure.

Such superatmospheric pressure may be as low as a fraction of an ounce per square inch above the pressure of the surrounding atmosphere adjacent the craft. Such low superatmospheric pressure may be maintained on all of the embodiments herein disclosed. This low differential of a fraction of an ounce per square inch permits the curtain to yield in a surprising manner when passing over obstructions without damage to the curtain or to the remainder of the craft. However, higher superatmospheric air pressures may be used when desired.

The construction is such that it automatically raises itself and a load from the "ground" surface when the blowing means starts. It correctly shapes and forms the curtain by automatic reaction, and automatically lowers itself when the blowing means stops.

Preferably the curtain is supported at its upper edge by the supporting member and has an outer, substantially vertical wall and an inner wall which extends upwardly and inwardly from the lower edge of the outer wall into the air cushion. The

air of the main part of the air cushion flows freely in and out of the space between the inner and outer walls automatically to fill such space with air at superatmospheric pressure and to cause the air cushion to raise the structure from the "ground".

5 The curtain provides a large vertical clearance above relatively high obstacles over which the structure may glide without perceptible impact, since the curtain is very flexible and adjusts itself for yielding movement over such high obstacles.

10 The slanting construction of the inner wall of the curtain readily permits it to pass over such objects both while the objects enter into and leave the space inside the curtain. The lower part of the air cushion is free of internal members with which such objects could otherwise collide. This permits the structure to pass over rough "ground" surface and high obstructions without damage or jarring effects on the structure.

15 The construction of the curtain is such that it automatically restores itself to normal operating condition if relatively high objects are encountered, or if the structure is temporarily tilted.

20 In some embodiments of this invention, the structure may be given a horizontal or sidewise movement by tilting the structure. The relatively high curtain height makes it possible to provide a sharp tilt, such as 20°—30° from horizontal position, which allows forward motion, sidewise motion, backward motion, or braking action, even on steep hills and the like.

25 The words "ground" surface as generally used herein are intended to include the surface of a body of water, floors, or any other surface over which the structure of this invention is to glide or hover.

30 Wheels or skids may be provided which can be lowered, if desired, either by deflation of the air cushion, or by proper linkage while the air cushion is maintained.

35 The structure of this invention permits a gliding action over water, and the curtain structure readily adjusts itself to wave motions and the like.

40 The structure may be used for interchangeable use over land and water, and it may readily pass from one to the other, and vice versa.

45 If desired, a plurality of concentric or otherwise nested curtains of this invention may be used together under a single supporting member, ramp, or platform, to produce a gradual restraining air flow out from the central part of the structure, under the plurality of concentric or otherwise nested curtains.

50 The invention may be embodied in all sizes. For example, it may be made with supporting platforms of from a few inches to many feet in lateral dimensions, as desired.

55 This invention is applicable also for general transportation or supporting action. It may be applied to transportation over land and/or water by many types of vehicles, such as passenger, freight vehicles of the automotive and/or trailer type.

In some of the embodiments of this invention, the aerodynamic lifting device may include a lifting platform having a relatively rigid supporting member with a peripheral orbital support for the curtain. An orbital, flexible, channel-shaped, sheet curtain may be provided with an outer edge secured to the peripheral orbital support and with an inner edge secured to a support inside of the peripheral orbital support and under said rigid upper supporting member. The curtain may have an intermediate low periphery between said inner and outer edges and there may be a peripheral air space between said curtain edges, and there may be a core air space inside of said inner edge. A superatmospheric pressure air

60 supply means is provided to introduce superatmospheric air into said spaces to form an air cushion below said supporting member to lift said supporting member with said intermediate low periphery of said curtain spaced slightly above a ground surface which is under said lifting device.

65 70 Some of the features of this invention are applicable to a lifting device in which the relative vertical distance or extent of the curtain need not be as high as in other instances. The relative height of the flexible curtain may be chosen to provide the desired lift or clearance of the supporting member above the ground surface.

The orbital, flexible, channel-shaped, sheet curtain may be V-shaped, U-shaped, or of other channel shape construction, depending upon the height of the curtain, the strength of the flexible material, and other factors, as desired.

The peripheral air space and the core air space may have superatmospheric air at substantially equal pressures. If desired, such air spaces may be interconnected or separated. The air-supply means for such air spaces may be effective to start and stop substantially simultaneously the air supply both of said air spaces.

Also, if desired, a plurality of curtains, side by side, may be placed under a single supporting member, ramp, or platform and the like, to support the same in a similar manner.

For example, in certain embodiments a plurality of such flexible curtains may be secured to and depend from the supporting member in such a manner that the supporting member does not tend to tilt when the load upon it is off center. In such embodiments, the curtains may be of substantially equal size, if desired, and tend to resist any tilting action. In such embodiments, if it is desired to provide self-propelling and guiding means, such means may take the form of jets, and the like, which may be supplied with superatmospheric air, either from the air supply to the curtains, or from a separate air supply or separate air blower or blowers, which may be used solely for the jet action, as desired.

Accordingly, it is among the many objects of this invention to provide vehicle, craft, or glider which embodies one or more of the novel features and/or methods herein disclosed. Other objects are apparent from this description and/or the accompanying drawings, in which:

FIG. 1 is a plan view, with parts broken away, of one embodiment of this invention.

FIG. 2 is a cross section along the line 2-2 of FIG. 1.

FIG. 3 is a side elevation of one of the skids, with many parts omitted, except the top panel member.

FIG. 4 is a top plan view of the embodiment of FIG. 1, showing controls which may be added thereto.

FIG. 4A is a perspective view of a modified form of the invention shown in FIG. 1.

FIG. 5 is the vertical cross section of a representative embodiment to which certain additions have been applied.

FIG. 6 is a cross section showing the formation of a curtain according to the present invention from a band of material.

FIG. 7 is a top plan view of another embodiment of this invention.

FIG. 8 is an elevational view of the embodiment of the present invention shown in FIG. 7.

FIG. 9 is the cross section along the line 9-9 of FIG. 7.

FIG. 10 is the diagrammatic representation of any of the embodiments of this invention passing over a relatively high object.

FIG. 11 is a plan view of another embodiment of this invention.

FIG. 12 is a cross section along the line 12-12 of FIG. 11.

FIG. 13 is an elevational view of a portion of the embodiment of the present invention shown in FIGS. 11 and 12, as viewed from the line 13-13 of FIG. 12.

FIG. 14 is a side elevational view of the embodiment of the present invention shown in FIGS. 11 to 13, showing the front end tilted down and the rear end elevated, to produce a forward motion.

FIG. 15 is a front elevational view showing the embodiment of FIGS. 11 to 13, with one side tilted down and the other side tilted up to produce a sidewise motion.

FIG. 16 is a diagrammatic illustration of a control for the rudder vane construction of FIGS. 11 to 13.

FIG. 17 is a diagrammatic illustration of the controls for the elevator-depressor vanes of FIGS. 11 to 13.

FIG. 18 is a diagrammatic illustration of the controls for the aileron vanes of the embodiment of the present invention shown in FIGS. 11 to 13.

FIG. 19 is a plan view of an embodiment of the present invention similar to that disclosed in FIGS. 11 to 18 but showing, diagrammatically, a weight construction which may be

moved in any direction to tilt the embodiment in any direction desired.

FIG. 20 is a diagrammatic illustration of one method of moving the weight constructions of FIG. 19 in any desired direction.

FIG. 21 is a plan view of another embodiment of this invention.

FIG. 22 is a cross section along the line 22-22 of FIG. 21.

FIG. 23 is an end elevational view of the embodiment of the invention shown in FIGS. 21 and 22.

FIG. 24 is a side elevational view showing the embodiment of FIGS. 21 to 23, with the curtain collapsed and the embodiment resting on skids or the like.

FIG. 25 is a diagrammatic representation of another embodiment of the present invention somewhat similar to FIG. 12.

FIG. 26 is a diagrammatic view of still another embodiment of the present invention including a plurality of units.

FIG. 27 is a diagrammatic view in vertical section of another embodiment of the present invention.

FIG. 27A is a fragmentary view in vertical cross section of a modified curtain construction according to the present invention.

FIG. 28 is a fragmentary elevational view partly in section showing an additional feature for the embodiment of FIG. 12.

FIG. 29 is a vertical view, partly in section, of another embodiment of the present invention.

FIG. 30 is a vertical view of still another embodiment.

FIG. 30A is a side elevation view of a modification of the embodiment of the invention shown in FIG. 30.

FIG. 31 is a plan view of a modification of the embodiment of the invention shown in FIG. 30.

FIG. 32 is a fragmentary diagrammatic vertical view of an embodiment of the present invention having a single wall curtain.

FIG. 33 is a view similar to FIG. 32 showing still another embodiment of the present invention utilizing a single wall curtain.

FIG. 34 is a plan view of another embodiment of the present invention.

FIG. 35 is a vertical cross section along line 35-35 of FIG. 34.

FIG. 36 is a horizontal cross section along line 36-36 of FIG. 35.

FIG. 37 is a diagrammatic horizontal cross section on reduced scale showing another embodiment of the present invention somewhat similar to that shown in FIG. 36.

FIG. 38 is a diagrammatic vertical cross section along line 38-38 of FIG. 37.

FIG. 39 is a view somewhat similar to FIG. 37 but showing a different embodiment of the present invention.

FIG. 40 is a diagrammatic vertical cross section along line 40-40 of FIG. 39.

FIG. 41 is a view somewhat similar to FIGS. 37 and 39, but showing a different embodiment of the present invention.

FIG. 42 is a diagrammatic vertical cross section along line 42-42 of FIG. 41.

FIG. 43 is a diagrammatic top plan view of another embodiment of the present invention.

FIG. 44 is diagrammatic top plan view of another embodiment of the present invention.

FIG. 45 is a diagrammatic vertical cross section showing an independent air supply for directional propelling jets of the character shown in FIGS. 34 and 35, and applicable to any desired embodiment of the present invention.

FIG. 46 is a diagrammatic representation viewed in plan of an actuating system for the directional and propulsion controllers of the embodiment of the invention shown in FIG. 34.

FIG. 47 is a diagrammatic vertical cross section along line 47-47 of FIG. 46.

FIG. 48 is a diagrammatic view in plan similar to FIG. 46, but disclosing an electrically powered actuator.

FIG. 49 is a top plan view showing blower and motor controllers substituted for the jet controllers of FIGS. 46, 47 and 48.

FIG. 50 is a horizontal cross section of another embodiment of the present invention taken along the line 50-50 of FIG. 51.

FIG. 51 is a vertical cross section taken generally along line 51-51 of FIG. 50.

FIG. 52 is a vertical cross section taken generally along line 52-52 of FIG. 50.

FIG. 53 is a horizontal cross section taken generally along the line 53-53 of FIG. 51.

FIG. 54 is a top plan view of the embodiment of the present invention shown in FIGS. 50 to 53.

Various words implying direction and the like, such as "horizontal", "upper", "lower", "vertical", are used herein for the sake of brevity, and it is to be understood that the devices described by such words may have other directions and positions.

Referring first to FIGS. 1-3, a structure 30' or lifting platform having a relatively rigid supporting member is supported slightly above the "ground" surface 30 by an air cushion formed by a peripheral air space 38, a plenum chamber 36 and a core air space 34 during normal operation of the structure. Air moving means or superatmospheric pressure air supply means in the form of a centrally located blower or fan 40 and a motor 42 are supported by the relatively rigid supporting member, including an upper horizontal panel 44 and an enclosing side wall or peripheral orbital or circular support 46 which forms the plenum chamber 36 of the air cushion. The motor 42 and fan 40 are supported by wires or springs 48 from the members 74 in any suitable manner. The air blowing means 40 has an air intake means or collar 50 with an inward flange 51, and the blower is connected with the surrounding atmosphere 52 and discharges air from said surrounding atmosphere 52 at superatmospheric pressure into said plenum chamber 36 which is part of said air cushion. This maintains the air of the air cushion in air spaces 34, 36, and 38 at superatmospheric pressure.

A flexible, hollow, columnar diaphragm curtain 54 may be an orbital, flexible, channel shaped, sheet curtain which may be of any suitable horizontal cross section, which, in this embodiment, is orbital or circular. The curtain 54 is sealed to, and is suspended from, the peripheral side wall 46 of the supporting member 44, 46, and surrounds at least the lower part or core space portion 34 of said air cushion spaces 34, 36 and 38. The curtain 54 has its lower edge 56 slightly spaced at 58 from said "ground" surface 30, during normal operation for restrained escape of air, as indicated by arrow 60 from said air cushion air spaces 34, 36 and 38 between said lower edge 56 and said ground surface 30.

The curtain 54 may be a double-walled orbital, channel shaped sheet curtain which has an outer wall 62, which may be substantially circular in horizontal cross section in this embodiment and an upper edge which is secured and suspended at 64 from the side wall or orbital support 46 and extends to the lower edge 56, which is the intermediate low periphery of the curtain.

The outer wall 62 has a sidewise extension, bend, or member 66 by which the inner wall 68 is joined to the outer wall 62. The inner wall 68 slants inwardly and upwardly from the lower edge 56 of the curtain 54 to an inner upper edge 70 which is suspended on a support or ring 71 inside the vertical bounds of said peripheral support 46 and within the upper part of the air cushion air space 34 and is spaced from the horizontal panel or platform 44 so the air of the main spaces 34, 36 of the air cushion flows freely in and out of the space 38 between the inner wall 68 and the outer wall 62.

The curtain 54 of this embodiment, and the curtains of the other embodiments herein disclosed, are relatively very thin in comparison to their other dimensions. They preferably are made of thin, flexible, air-impermeable, relatively non-stretchable material, such as a plastic material with or without reinforcing threads or other reinforcing strands molded in it.

For example, for the curtain 54 of this embodiment of the size specified, the material may be made of polyethylene film and the like of 12 mils (.012 inch) thickness. Other sizes and embodiments may have curtains with the same or proportionally varied dimensions of thickness.

Generally, the film for this and other embodiments is so thin, compared to its width or length, that it may be relatively non-self-supporting in an edgewise direction.

The material for all of the embodiments may be flexible plastic, such as polyethylene or Mylar, thin rubber, or the like, with nylon or other strong threads or other reinforcing strands molded in it to render it relatively nonstretchable.

The curtains of all of the embodiments are subjected to a relatively low pressure differential between the inner superatmospheric pressure in the air cushion and the atmospheric pressure of the surrounding atmosphere. Such pressure differential between the air in the cushion and the air in the surrounding atmosphere may be as low as in the order of a fraction of an ounce per square inch, or more.

The material for the curtain of any of the embodiments may be cloth made substantially impervious by treatment such as by plastic impregnation and the like. It may be similar to impregnated cloth now sold for kitchen tablecloths, and the like, of a sufficiently flexible type capable of hanging of its own weight as a straight cylindraceous or cylindrical curtain.

The air cushion formed by air spaces 34, 36, 38 is substantially free of unyielding obstructions a substantial distance above the lower edge 56 of the curtain 54 so the structure may pass freely over relatively high objects, such as large stones 72, and the like, as shown in FIG. 10. The slant of the inner wall 68 permits the stone 72 or high object to pass outwardly from the curtain 54 as well as inwardly, as the craft passes over the stone.

The ring 71 is secured to two horizontal cross members 74 which are supported on the side wall 46, by way of example. The relative height of the curtain may be varied, depending on the clearance height desired.

A plurality of skids 76 may be secured to the ring 71 and may extend to the upper panel 44, if desired, as indicated at 77. These skids support the rigid structure slightly above the "ground" surface 30 when it is not in normal operation in substantially the same manner as in FIG. 24. The skids all extend in parallel direction with the inverted arches 76A extending parallel to the forward motion of the car.

If desired, a seat 78 may be placed on top of the panel or platform 44. Such seat may be supported on upright bars or columns 80, which may be secured to the collar 50, and horizontal bars 82 extending radially inward from the bars 80.

A suitable size for this embodiment is 8 feet in diameter at the side wall 46. The side wall 46 may be 18 inches in vertical extent. The curtain 54 may be 26 inches from the lower edge 56 to the upper edge 64.

In general, the height of the curtain 54 may be 20 percent-30 percent of the diameter of the side wall 46 and the spacing of the upper edges 64 and 70 has operated successfully when it is approximately 10 percent more or less of such diameter.

The above dimensions are given by way of example only and not by way of limitation of the broad principles of this invention.

When the structure of FIGS. 1-3 is not operating, it rests on the "ground" surface 30 on the skids 76. If the operator desires to ride, he sits on the seat 78 and closes a switch, not shown, which energizes the motor (if electric) through the medium of a long electric cord which is connected to a source of power and to the motor. This causes the blower or fan 40 to rotate. A gasoline engine, self cranking if desired, may be used in lieu of the motor, and may also be started by a cranking switch.

Air from the surrounding atmosphere 52 is withdrawn through inlet defined by the collar 50 and is discharged by the blower 40 into the air cushion spaces 34, 36, 38 at superatmospheric pressure. The structure then quickly rises from the

stationary position, similar to that shown in FIG. 24, to the position of normal operation shown in FIG. 2. The lifting force produced is believed to be equal to the area of the "ground" surface 30 which is enclosed by the circular edge 56 multiplied by the pressure difference between the surrounding atmosphere pressure and the effective superatmospheric pressure within the air cushion spaces 34, 36 and 38. This pressure differential presses up against the horizontal components or vectors of the structure, such as panel 44.

The outer curtain wall 62 automatically becomes substantially perpendicular by automatic correct bend at 66 by forces which are believed to depend on the relatively high superatmospheric static air pressure inside the space 38 near the bend 66 and the relatively lower superatmospheric air pressure at the outlet space 58 where such lower pressure is caused by the pressure drop due to the "Venturi" velocity effect as the superatmospheric air flows outwardly to the outside atmosphere. This pressure differential above and below bend 66 pushes the curtain 54 downwardly and maintains the walls 62 and 68 in tight condition with the wall 62 in perpendicular or cylindrical condition. This provides a relatively large "ground" surface area inside the lower edge 56 which provides the surprisingly high lifting force of the construction.

After the construction has been lifted to the position of FIG. 2, with the space 58 being between 1½—2½ inches, such construction glides freely sidewise over the "ground" surface seemingly in a friction free manner. Very little force is required to move the construction over substantially level ground, and it glides down inclines at surprising speeds. Normally, the weight of the machine and the parts thereof are symmetrically distributed about a central vertical axis, so there is no tilting action produced in the machine.

A lateral force may be imparted to the construction by applying a weight construction of any desired shape on or below the supporting member 44 sufficient to depress slightly one side of the structure. This causes a larger amount of air to pass out through the opposite side of passageway 58, the reaction of which causes the structure to move toward the depressed side. (See FIGS. 14 and 15 for similar reactions.) The weight may be a separate weight which may be provided with sidewise adjusting means or the operator may use the weight of his own body and may lean toward the direction of the side to be depressed and toward the direction of travel desired.

FIG. 4 shows a plurality of propulsion and directional controls used on the embodiment shown in FIGS. 1, 2, and 3. These propulsion and guidance members or means may be manually adjusted if the embodiment, for example, is a toy or lecture educational device. The controls may be used all simultaneously, less than all may be used simultaneously, or any one of them may be used alone in order educationally to illustrate the various principles involved in the propulsion and guidance of the apparatus. These means may have sufficient frictional resistance to adjustment, or may have clamping means, so that the controls remain in the positions selected by the user when he is manually adjusting them to the desired position.

On the other hand, if desired, these propulsion and guidance means may be controlled from a distance by actuators of the type referred to, which are similar to automobile, electric or hydraulic window-lifters and/or airplane "actuators" of the type herein elsewhere referred to. For example, each of the movable parts of the propulsion and guidance members may be actuated by small electric motors, in combination with suitable levers, gears, for example of the worm type, and the like, which can be proportionally controlled by suitable levers and the like, within reach of an operator who may be riding on the device. Stop limit positions may be provided, and slip clutches may be used between the motors and the controlled devices, so the devices stop at a desired effective position regardless of how long the switch or the like is closed. Since these actuators, of many different types, have now acquired a distinct status in the arts, it is deemed unnecessary to illustrate each of them specifically since they may

be supplied by any of the many sources of supply of these items. An exemplary number of such remote controls have been illustrated to enable those skilled in the art to use either the illustrated exemplary remote controls or any other type of remote controls now on the market.

The weight construction may take the form of a plurality of weights 59, FIG. 4, which may be equally spaced about the central axis of the embodiment. The weights may be located in the plenum chamber 36, if desired. This feature may be used in all embodiments, where applicable. These weights may be shifted, simultaneously if desired, to positions such as 59A or any other similar position to cause the craft to move in the direction of the shift. An example of the weight construction and the shifting means is illustrated in FIGS. 19 and 20 in connection with another embodiment, but such construction of the weights in FIGS. 19 and 20 obviously is applicable to any other embodiments herein disclosed. All of the weight portions 59 and 59A are shown in dotted lines since the weights may be located underneath supporting member 44.

Other methods of producing lateral travel are applicable to all of the embodiments and may include the use of an air propeller 59B, FIG. 4, independently driven on top of the panel 44 by motor 59C which is rotatably mounted on a vertical axis 59D to be free to be directed in any direction desired. Also, a plurality of air escape orifices or tubes may be additionally or alternatively provided in the side wall 46 as shown at 59E and 59F so the reaction of the flow of air out through such orifices or tubes may cause any desired reaction, such as lateral tilting and turning movement. Rudders, lift or depressing vanes and closing vanes may be provided at such orifices or tubes to regulate the effect of such forces, and to control the volume of air discharge through such orifices.

For example, the orifices 59E may be provided with opening and closing vanes or valves 59G, one or more of which may be opened to produce forward or sidewise motion. In addition, the orifices 59E may be provided with horizontal vanes 59H which may produce a lifting or depressing action when such vanes 59H are tilted up or down, while the accompanying valve 59G is opened. The orifices 59F may be provided with rudders 59I which may be turned about a vertical axis. These orifices 59F may also be provided with valves 59J for opening and closing the orifices 59F. The rudders 59I may be used to turn the craft, to direct it in any desired direction. In addition, such rudders may be used to produce a slight counter torque effect to neutralize the slight turning effect which is produced by the torque reaction from the motor 42 and blower 40. Any of the controls shown in FIG. 4 are applicable to any of the embodiments herein disclosed, where the same are applicable, and these controls may be in turn controlled by any well known and conventional actuators, such as wire actuators, hydraulic actuators, electric actuators, and the like, which may be controlled by the operator of the vehicle, as before explained.

The curtain 54, being substantially impervious to air, retains the superatmospheric pressure air within the air cushion air spaces 34, 36, 38 so it can only escape at the narrow space under the lower intermediate peripheral edge 56 of the curtain. This permits the main supporting body 44, 46 to be relatively high off the "ground" surface without loss of lifting power which would otherwise occur if the impervious curtain were not there to prevent dissipation of the high pressure air through the large gap between the lower edge of the side wall 46 and the "ground" surface 30. That is, the curtain 54 adds its height to the permissible height of air escape space 58 adjacent the "ground" surface. In this case, it adds 26 inches to the permissible 1½—2½ inch space 58. Without the curtain 54 of this invention, the lower edge 64 of the rigid wall 46 would have to be within 1½—2½ inches of the ground surface. Such rigid wall 46 would not yield when encountering a stone or the like, so the vehicle would have to stop suddenly or the wall 46 would be broken. The gliding action shown in FIG. 10 is not possible without the curtain of this invention.

The motor 42 may be replaced by an internal combustion engine, such as a gasoline engine, with a vertical drive shaft. If desired, such gasoline engine may be located below or above the panel 44 and may be supported on it by suitable brackets, etc. Such engine may be located above the panel 44 and beneath the seat 78, if desired.

Under certain conditions, the outer curtain wall 62 alone may be used without the inner wall 68. Under such conditions means may be provided to produce a downward pull at the bottom of the curtain; such means may be a flexible lateral enlargement, bead, flange, or the like, which may be provided at the lower edge 56. This may take the form of a flexible rope or tube to which the edge 56 is attached. Such tube may be inflated, if desired.

The principle of the bead enlargement or the like, as illustrated in FIGS. 32 and 33, may be embodied in a flexible rope 560 (FIG. 32) or tube 562 (FIG. 33) secured to the bottom edge of a single outer cylindrical or columnar curtain wall 564 which may be used with all of the embodiments herein disclosed, where applicable. The result is to produce a downward pulling action on the lower edge of the single outer wall 564 which is produced by the slightly lower superatmospheric air pressure in the space 566 between such rope, tube or other flange and the "ground" surface 568 below such edge as compared to the superatmospheric pressure of the cushion 570 on the upper inner side 572 of such rope, tube, or other flange. That is, a somewhat similar "Venturi" effect is produced along said bottom edge of the rope, tube, or flange of the curtain which reacts with the higher pressure of the air cushion 570 on top of the inner part of rope, tube, or other enlargement to pull the curtain down to keep it in columnar condition.

The curtains 564 of FIGS. 32 and 33, as well as all other curtains herein disclosed, are particularly advantageous when such curtains are cylindrical or substantially so.

A substantially cylindrical or circular cross section for the outer wall of the V-type of curtain of FIGS. 1-31 and for the single wall type shown in FIGS. 32 and 33 is particularly advantageous. The small air pressure differential (of a fraction of an ounce per square inch, for example) between the superatmospheric air pressure on the inner side of such curtain wall and the surrounding atmospheric air pressure on the outer side of such wall permits such wall to yield to inward impulses from rocks and other obstructions with surprising ease with practically no resistance and with no perceptible jarring effect and/or wearing effect on the curtain wall. This small pressure differential is evenly distributed around the periphery of such cylindrical curtain so that an even and easy pull is produced throughout the curtain. This permits the use of such relatively thin curtain material.

The cylindrical or cylindraceous shape of the outer wall permits substantially the entire lifting thrust reaction of the air cushion to be applied only to the solid support member (member 44, for example) without imparting any of such lifting thrust to such cylindrical or cylindraceous wall. This keeps a minimum thrust on such curtain wall and only the horizontal outward thrust is applied to such curtain wall, while the entire lifting thrust of the air cushion is applied to the horizontal components of the support member (such as 44) and not to the curtain. The cylindrical or cylindraceous shape of the curtain wall distributes this horizontal thrust evenly over the entire cylindrical surface of such wall, so no undue thrust is produced on the fabric. The curtain wall can, therefore, be made of the thin material elsewhere described with all of its attendant advantages.

A lateral deflector 81, FIG. 2, of cone-like shape may be provided to produce an outward flow to the air discharged by the fan or blower 40. This causes the deflected air to flow toward the space 38 to insure that the superatmospheric air pressure therein is properly maintained to cause the curtain 54 to be downwardly pushed against the reduced air pressure underneath the annular space 38. Deflectors of this or other types may be used in all of the embodiments, when desired.

In the embodiment shown in FIGS. 7 and 8, the platform 44A and the side wall 46A may be equilateral and octagonal in horizontal cross section, which is substantially circular for all practical purposes. In the size herein used, the number of sides 8 of the polygon is sufficient to cause the octagon to "approach" or be similar to the circumference of a circle, according to a principle well known in mathematics, which has been used, for example, in the solution of many problems concerning the circumference of a circle. The dimensions may be 8 feet in horizontal direction between opposite sides 46A, and 26 inches in height at the outer curtain wall 62A. The internal combustion engine 42A may be a gasoline engine of the vertical shaft type, such as is now extensively used to drive lawn mower fan-like cutting blades which rotate about a vertical axis, and the like. The engine may be of one or more horsepower, as more fully elsewhere specified.

Other parts which are substantially similar to those disclosed in connection with FIGS. 1-4 are indicated with reference numerals corresponding to those in FIGS. 1-4. However, generally the letter A is added. The operation is the same as in FIGS. 1-4.

The curtain of FIGS. 7-9 is generally octagonal at the upper end, which is substantially circular in cross section for all practical purposes, according to mathematical principles, and assumes practically a circular cross section at the bottom edge 56A, to produce a cylindraceous curtain.

The operation is substantially the same as in FIGS. 1-4. The internal combustion engine may be replaced by an electric motor, or the like, either above or below the top plate or platform 44A.

The ring 71A may be generally octagonal, or circular, if desired, and may be of generally flat cross section as shown most clearly in FIG. 9. It may be supported by cross members 74A, which may be similar to members 74 of FIGS. 1-4. All of the features, which are applicable and which are disclosed in connection with FIGS. 1-4, may be used in the embodiment of FIGS. 7-9.

In the embodiment just described, the craft floats on a low pressure air cushion using a high volume of air controlled by a high pressure air cushion enclosing curtain to reduce the velocity of air through the peripheral airstream that increases the phenomenon of lift or ground effect.

The craft is 8 feet from side to opposite side, and is powered by a vertical shaft gasoline engine of the type now extensively used on vertical shaft lawn mowers. For example, a gasoline engine of this type that develops 1 horsepower at 1400 RPM, which is the speed that it turns the 24 inch, six blade fan at full throttle, has been found satisfactory. This combination lifts the weight of the air car which is 175 pounds, plus over 500 pounds of load or passengers.

The columnar air cushion enclosing curtain on this craft is made of 12 mils (.012 inches) polyethylene material and when airborne hangs down 26 inches from the lower edge of the craft, then it is turned in and upward in a V-shape and is attached to an inside rim level with the outside bottom rim of the craft and 10 inches more or less in from the outside edge. This makes each side of the V-shape of the curtain 26 inches and the opening at the top of the V ten inches across, more or less. The inside edge of the air cushion enclosing curtain is 4 inches below the underside floor of the craft, which lets the air pressure pass above it and get inside the V. This builds the air pressure inside the air space 38A in the curtain. That, in turn, is the supporting factor that makes the craft carry the enormous lifting power that it does. The outside of the curtain V is substantially vertical and the inside of the curtain V is upward at about 30° inward from vertical. Another purpose for the V in the curtain is that it allows the curtain to pass easily over objects when the craft is in motion. A single straight curtain hanging down from the craft would swing it over an object, but the opposite inside of the straight curtain would hang on the object as the craft passed from over the object. But, having the V curtain at the opposite side, the curtain rises against the slant and passes over easily. The curtain, being flexible, allows

the craft to be tilted against sloping surfaces, thus making air cushion vehicles adaptable to uses over surfaces with as much as up to 30° inclines, whereas a rigid frame air cushion vehicle cannot negotiate more than a 5° incline without bumping its nose against the surface. Even this rate of incline would require tremendous horsepower in the rigid rim vehicle. The opening at the top of the V in the air cushion enclosing curtain will be greater as the length of the curtain is increased. Both the length and opening of the curtain are governed by the amount of power used in the craft as well as the size of the craft.

The flexible curtain can be made of material other than polyethylene. Some other material, such as flexible plastic such as Mylar and the like with nylon or other threads molded into it, provides more durability and strength. A thin rubber material with a nylon thread may also be used.

When in use over water, which also is intended to come under the definition of "ground effect", the V shape of the air cushion enclosing curtain acts as a float like an inflated inner tube in the event the craft is overly tilted and any side makes contact with the water. Otherwise, when operated over water, the bottom edge of the curtain remains the same distance above the water as when it is operated over firm surfaces. The air cushion enclosing curtain holding the craft body a considerable distance above the water also serves to lessen the disturbance of the water as there is the mass pressure of air against the water instead of a jet stream being blown down into the water. The inner wall 68 may be provided with openings slightly above the lower edge of the curtain, which permit the water to be drained.

In the propulsion of the craft, there are several methods. In addition to having the intake fan in a vertical shaft position, the intake fan performs equally as well in a horizontal shaft position in the front or rear, or, with an intake fan in both front and rear in a horizontal shaft position. Because the craft operates on a sidewise thrust of air pressure rather than only on a jet stream blowing down around the outer edge perimeter, it is possible to position the intake of the fans in the ends of the vehicle. The fans may be driven by a central motor or by a motor for each fan. So there is added another method of propulsion by such construction.

With the horizontal shaft positioning of the intake fans in the ends, the individual fan lifting effort requires less than half the power, so by powering the intakes at 50 percent, the craft hovers. Then, by increasing the intake power of the front fan, it pulls the craft forward, gaining momentum as it goes. For braking or stopping, the power of the front motor or fan may be decreased to about half, and the power of the rear motor or fan may be increased until the forward motion is stopped. If the operator then equalizes the power of both motors or fans about half, the craft hovers. In addition to this method of propulsion and stopping or braking, there may be provided exhaust jet louvers, substantially similar to the air escape orifice construction 59E and valve construction 59G illustrated in, heretofore described by reference to FIG. 4, in both front and back vertical surfaces of the craft which, by opening the back jet louver, a jet stream of air will force the craft forward. For stopping, close the rear jet and open the one in front and that will retard the forward speed. The air for use through the jet louvers can either be taken from the air mass that suspends the craft, or be provided by auxiliary fans located in channels independent of the main air cushion mass.

Another method of propulsion and control is by movement of the inside ring 71 or 71A to which the flexible curtain is connected. It may be movable on gimbals as diagrammatically illustrated in FIG. 4A so any side of the perimeter can be raised or lowered, which, in effect, shortens the flexible air enclosing curtain on that side of the craft. This automatically tilts the underside lifting area of the craft and causes the craft to move in the direction of the shortened side of the flexible air curtain. A reversing of the procedure, once the craft is in a forward motion, causes a braking or stopping effect. A variation sidewise of the procedure augments the steering.

For a quick or emergency stop, there is provided a retractable skid or wheels with brake attachment, as illustrated in FIGS. 29 and 5, respectively, and the pressing of a foot pedal will lower the skid or wheels to make contact with the surface and provide a quick stop.

In event that the intake fan is in a vertical shaft position, then the propulsion may be by the jet louver principle with the skid on wheels with brake for the stopping power, or the principle explained in the above paragraph of shortening the air curtain on a movable perimeter for directional tilt of the craft for all three items of propulsion, guidance, and braking power.

As will be more fully described hereinafter by reference to the embodiment of the invention shown in FIGS. 11-18, for the control of the craft with the intake fans in a horizontal position in front and/or back, there is a method of guiding and controlling the craft by placing a rudder fin and elevator fin in the intake jet stream of air that the fan is drawing in, and the elevator and vertical fins being in the slipstream of the fan, makes the guidance of the craft similar to the reactions of the controls on a plane. This arrangement also causes stability in keeping the craft level, or to raise or lower each of the ends of the craft if a tilted position is needed to aid in the forward, backward, or sidewise movement to secure controlling action.

The curtain construction for the embodiment of this invention may be made by forming a cylinder 100, FIG. 6, as by sealing together at 102 the opposite ends of a long rectangular band of material. One end 104 of such cylinder may then be secured to the lower edge of the plenum chamber at the joint 64. Thereafter, the other end 106 of the cylinder may be turned in, pleated, and secured to the ring 71. The pleats formed by their turning in operation are indicated by dotted lines 108.

FIG. 5 discloses features which are applicable to the embodiments of this invention. For example, a pontoon construction 150 may be secured or attached to any of the embodiments of the present invention. The pontoon has sufficient water displacing capacity to maintain the craft afloat with all expected loads thereon. Such pontoon construction 150 may take the form of the cross section shown in FIG. 5, and may be attached to the sidewall 46, which may be the sidewall of any of the embodiments. The pontoon construction may be detachably secured to the wall 46 by any suitable means in end to end relationship, completely to surround the embodiment if desired.

The pontoons 150 preferably are constructed so a large amount of displacement of water is displaced adjacent the lower part of the wall 46 in order to maintain as much of the plenum chamber 36 above the level of the water.

The cross members of any embodiment, such as cross member 74 of FIGS. 1 to 4, may be placed at a higher level than the level of such members in FIGS. 1 to 3. In this manner, the upper edge 70 of the curtain 54, and its supporting ring 71, may be at a relatively high position within the plenum chamber 36. This prevents any substantial amount of water from splashing over the upper edge 70 into the space 38 by wave action and the like.

If desired, a series of openings 38J may be produced in the inner wall 68 near the bottom of such wall. These orifices 38J are sufficiently small to prevent any substantial amount of water from being splashed into the space 38, but they are sufficiently large and sufficiently low in position, substantially to drain the space 38 of water if any splashing should occur over the ring 71 and to permit the drainage of the space 38 when the craft is first operated from a standing position. Alternatively or additionally, the openings 38J may be omitted and a bilge pump may be provided, with its intake pipe properly shaped and relatively low in the space 38 and near the bend 66 so that such bilge pump can substantially empty the space 38.

Skids 76 may be provided, substantially the same as the skids 76 of FIGS. 1 to 3. Alternatively, or additionally, four aligned wheels 76J may be retractably supported by a holding and retracting mechanism 76I, which may be supported from

the panel 44 by any supporting member 76K. When the wheels 76J are in their lower position, they raise the craft sufficiently high so that the skids 76 do not touch the ground. When the wheels 76J are retracted upwardly, to the dotted line position, the skids 76 may support the craft. When it is desired to stop the craft, the blowing means may be stopped, whereupon the curtain 54 deflates or folds, so that the wheels 76J will engage the ground and hold the craft slightly spaced from the ground. The wheels 76J may be provided with brakes 76M as are well known and of conventional construction to stop the forward or backward movement of the craft when it is lowered while it is in forward or backward motion. When it is desired to stop the craft more vigorously, the wheels 76J are retracted upwardly, and when the curtain 54 is deflated by stopping the blowing means, the skids 76 engage the ground and stop the craft within a short distance. Three or four wheels 76J may be provided, all in parallel relationship, and directed in a direction parallel with the forward and backward normal direction of the craft.

All of the features of FIG. 5 are applicable to all of the embodiments herein disclosed.

An embodiment is shown in FIGS. 11-18 which has air moving means in the form of two blowers 200 mounted on a structure 30C to produce an air cushion within the core air space 34C, the plenum chamber 36C and the peripheral air space 38C. The blowers 200 are driven by power means such as by internal combustion engines 42C which are supported from an upper horizontal panel 44C and inside an enclosing side wall 46C. The panel 44C and side wall 46C form the plenum chamber 36C of the air cushion.

For example, these engines may be approximately 9 horsepower gasoline engines of the type now being used on small tractors and the like. The blowers or fans may be from 18 inches to 24 inches in diameter. The craft may be from 9 to 10 feet in diameter.

A curtain 54C has an outer wall 62C and an inner wall 68C substantially the same in character as in the first described embodiment of FIGS. 1-4 to form the spaces 34C and 38C which are substantially the same as spaces 34 and 38 of the embodiment of FIGS. 1-3, and their operations are, therefore, not further described.

The panel or platform 44C has a depressed space or cockpit 202 formed therein by an air impervious wall extending downward to provide a cockpit which may be provided with a seat 204 for one or two persons or operators.

The blowers 200 are driven by the internal combustion engines 42C through the medium of drive shafts 242. The rotation of the engine shafts 242, the blowers 200, and the engines 42C is in the same direction, when viewed radially inward from the outside in alignment with the shafts 242. This type of rotation causes the torque effects of the two blowers and engines to counteract each other and neutralize the counter torque effect which each unit produces so no tilting action is produced on the craft by counter torque. Means are provided for neutralizing any counter torque effect which may be produced by operating the opposite blowers 200 in a manner to produce different counter torque effects as is elsewhere described.

The blowers 200 are surrounded by cylinders 206 which have air inlets 208 to draw air in from the surrounding atmosphere 52C and discharge it at superatmospheric pressure into the plenum chamber 36C so the plenum chamber 36C and spaces 34C and 38C contain air at superatmospheric pressure substantially as described in connection with the embodiment of FIGS. 1-4.

The air from the blowers 200 flows through the cylinders 206 in respective streams at relatively high speed as indicated by the arrows 260 and 262, respectively in FIG. 12.

Suitable controls, in the forms of vanes are placed in the air streams of cylinders 206 to produce identical power to maintain the craft stationary, or the blowers may be differentially operated to produce forward or backward motion as elsewhere described.

The vanes may take the form of elevator or depressor vanes 210, aileron vanes 212 and 214, and rudder vanes 216 and 218. One elevator or depressor vane 210 may be used in each cylinder 206. As best seen in FIGS. 12 and 13 two oppositely movable aileron vanes 212 and 214 may be used in each cylinder 206. One rudder, made up of two identically movable and rigidly connected vanes 216 and 218, may be provided in each cylinder 206.

The elevator or depressor vanes 210, when actuated from normal straight position, elevate one end and depress the other end of the craft for forward or backward movement or to compensate for inclines or hills in a forward or backward direction. The vanes 210 at each end of the craft may be maintained in substantially parallel relationship to produce this effect.

For example, a suitable actuator of any desired form may be provided by which the operator may actuate the vanes and engines in any desired manner. For example, such actuators may include levers, pedals, electric buttons, or the like, which can be moved by the operator and the corresponding engine, engines, vane or vanes is or are proportionally actuated. The levers, pedals, buttons, and the like, are connected to the element being actuated by suitable cables, wires, fluid conduits, electric conductors, and the like.

For example, a suitable manual control may be provided for moving the elevator depressor vanes 210 and the aileron vanes 212 and 214, as shown in FIGS. 11, 12, 17 and 18. This manual control may take the form of a universally movable, somewhat vertical stick 220 which is universally fulcrumed at 222. When the handle 224 of the stick 220 is moved forward or to the left in FIG. 12, the forward end 226 of the craft is depressed and the rear end 228 is elevated as shown in FIG. 14. When the handle 224 is moved backward, the rear end is depressed and the forward end is elevated. These elevating and depressing actions may provide, respectively, forward and backward movement of the craft without change of blower speeds, and this action may also compensate for hill and wave formations in a forward or backward direction.

Sidewise movement of the handle 224 may control the opposite movements of the ailerons 212 and 214 at opposite ends 226 and 228 to tilt the craft sidewise, as shown in FIG. 15, for sidewise movement of the craft. The sidewise movement in one direction of handle 224 depresses the side of the craft in that direction and vice versa.

An actuator in the form of a pedal rod 230, FIGS. 11, 12 and 16, fulcrumed about a substantially vertical axis 232 and is provided with pedals 234 and 236 for actuation by the feet of the operator for turning the rudder vanes 216 and 218. Forward movement of the left foot pedal 236 will cause the craft to turn leftward. Forward movement of the right foot pedal 234 will cause the craft to turn rightward. The rudder vanes 216 and 218 turn in the same direction since they are rigidly connected and mounted on the vertical shaft constructions 238', 238, respectively, which are rigidly joined together by a rigid box 240 which permits the drive shaft 242 of engine 42C to pass to the blower 200 while maintaining the vanes 216 and 218 rigidly joined together for movement in unison. Any other relationship between the movement of the pedal rod 230 and the movement of the rudder vanes 216, 218 may be substituted, if desired.

Any suitable actuator constructions may be used between the stick 220 and the vanes 210, 212, and 214 to produce the desired motion. Likewise, any suitable actuator construction may be used between the pedal rod 230 and the rudder vanes 216 and 218 to produce the desired motion.

By way of example, actuator constructions of the cable or wire type are illustrated, but other actuator constructions such as hydraulic or electric may be used. The wire ends preferably are connected to the corresponding vane constructions by strong tension springs, not shown, which permit a slight lengthening action, if necessary, when the cable or wire is moved sidewise incidentally to a linear or lengthward movement of the cable or wire.

A suitable actuator system for the elevator depressor vanes 210 is shown in FIG. 17. Such a system may include the stick 220 which is universally fulcrumed at 222. The lower end or arm 244 is attached to a cable or wire 246 which passes over as many pulleys 248 as may be required. This wire 246 is attached to the two vanes 210 at opposite ends 226 and 228 of the craft. The attachments may be located at 250 and 252 near the edges of the vanes 210 as shown, or may be attached to suitable levers on the shafts of the vanes as desired. Another wire 247 is attached at 250 and 252 to the vanes 210 and passes over as many pulleys 248 as required. Strong tension springs, not shown, may be provided between the ends of the wires 246 and 247 and the vanes 210 at the attachments 250 and 252. Such springs are sufficiently strong not to stretch perceptibly except when out of line movement of the arm 244 requires more length than the total lengths of the wires 246 and 247, such as by the out of line sidewise movement 254 or the out of line movement 256 and 258 at the vanes 210. However, such springs do not yield to true liner movement of the wires, as previously explained. The linkage is such that forward movement of the handle 224 causes the vanes 210 respectively to move to dotted positions 210A and 210B. The inward movement of air by the blowers 200, as indicated by the arrows 260 and 262, causes the front end 226 of the craft to be pushed down by the vane in the position 210A and causes the rear end 228 of the craft to be pushed up by the vane in the position 210B by such movement of air as shown in FIG. 14. The reaction of the large volume of air passing under the curtain edge 56C at end 228 causes the craft to move forward under normal conditions as indicated by arrow 264 as elsewhere explained. Movement of the handle 224 in a backward direction causes each of the vanes 210 to be oppositely inclined and causes the rear end 228 of the craft to lower and the front end 226 to raise to produce a braking or backward effect. Any other desired relationship between the movement of the stick 220, or any other type of automatic or manual control may be substituted, if desired.

A suitable actuator system for the aileron vanes 212 and 214 at each of the craft ends 226 and 228 may be provided, as shown in FIG. 18. For example, the same stick 220 which actuates the elevator depressor vanes 210 may be used to actuate the aileron vanes 212 and 214. When the stick 220 and handle 224 are moved sidewise to the left of the operator, the craft is tilted to the left as shown in FIG. 15 and vice versa.

For example, the lower end on arm 244 is attached to wires 270 and 272. These wires pass over as many pulleys 274 as is necessary and the wire ends are attached to the aileron vanes 212 and 214 at the respective craft ends 226 and 227. Counteracting wires 275 are attached to the vanes 212 and 214 and pass over pulleys 276. Movement of the stick 220 and handle 224 to the left of the operator, as shown in dotted lines, causes the aileron vanes to move the dotted line positions 212A, 212B, 214A and 214B. The inward movement of the atmospheric air by blowers 200 causes the ailerons to tilt the craft with the left side down and the right side up, as viewed from the cockpit 202 facing forwardly toward end 226 and as shown in FIG. 15. This causes a large volume of air to pass out the raised curtain edge 56C at the operator's right, and causes a retarding effect at the operator's left side, with a corresponding sidewise movement of the craft to the left. Movement of the stick to the operator's right causes an opposite effect on the vanes 212 and 214 with a corresponding opposite movement of the craft.

Strong compression springs of the character heretofore described, may be provided at the points of attachment of the ends of the wires 270 and 272 to the aileron vanes, which provide the same out of line yielding effect when necessary, but which do not yield to true linear movement. This permits the rod 220 to pull the wires 246, 270 and 272 sidewise slightly out of line by the slight yield of such springs but insures correct actuation in a linear direction along the lengths of these wires.

In FIG. 16 the pedal rod 230 may be attached at its ends 277 and 278 to wires 280 and 282, respectively, which pass out of the cockpit in substantially air sealed condition. The wires 280 and 282 may pass over the required number of pulleys 284. The ends of the wires 280 and 282 may be attached to the rudder vanes 218 (or 216) by strong tension springs, not shown, if necessary to permit a slight yielding action of the wires, by out of line movement of wires 280 and 282, but not by true linear movement. Forward movement of pedal 236 by the operator's left foot causes the wires 280 and 282 to move lengthwise as indicated by the arrows 286 with a movement of the rudder vanes 216 and 218 to the dotted positions 284. Inward flow of blower air, as indicated by arrows 260 and 262, causes the craft to turn toward the operator's left side, and vice versa. Any other relationship between the movement of the pedal rod 230 and the rudders 216, 218 may be used if desired.

Weights may be used to cause a forward, backward stopping, or sidewise action of the craft in addition to or alternatively with the vane constructions. For example, in FIGS. 19 and 20, a universally movable rod 290, with a handle 292 may be fulcrumed at 294 at the floor of the cockpit, if desired, and its lower arm or end 296 may be attached by strong tension springs 298 to the upper runs of the wire bands 299 and 301 which pass over the pulleys 303 and 305 respectively. The lower runs of these bands 299 and 301 are attached to the weights 307, 309, 311 and 313 which may be supported on suitable stationary slides 315 and 317 by pulleys, if desired. Sidewise movement of the rod 290 to the operator's right, as shown in dotted lines, causes the weights 307 and 309 to move to the operator's right to positions 307A and 309A. This causes the craft to lower its right side with a corresponding sidewise movement, and vice versa. A forward movement of the 290 causes the weights 311 and 313 to move forward with a corresponding downward movement of the craft's front side and with a corresponding forward movement of the craft, and vice versa. A diagonal movement of the rod 290, both forward and sidewise to the right, for example, causes a composite movement of weights 311 and 313 forward and weights 307 and 309 rightward with a corresponding movement downward at the front, right side and with a corresponding frontward and rightward movement of the craft, and vice versa. In this manner, the movement of the rod 290 in any desired direction causes a corresponding movement of the craft.

The strong springs 298 permit sufficient stretch due to out of line movement of the bands 299 and 301, but do not yield to true linear movement along the lengths of the wires, as previously described.

FIGS. 21 to 24 show another embodiment of this invention. A supporting member 300 has air-moving means in the form of a blower or fan 302 and an engine of the internal combustion type 304, if desired which is mounted adjacent the collar 306 with an inward flange 308. This air intake means construction is substantially the same as previously described in connection with FIGS. 1 to 3. A seat 310 may be provided, which is supported by vertical bars 312 and horizontal bars 314. The air intake means, defined by the collar 306 and flange 308, communicates the plenum chamber 338 with the surrounding atmosphere 316 so that operation of the blower 302 will effect the discharge of air from such surrounding atmosphere at superatmospheric pressure into a plurality of air cushions 318, 320, 322 and 324. Flexible, hollow columnar curtains are supported by the supporting means 300 at their upper edges. These curtains respectively surround at least the lower parts of the air cushions. These curtains are of the same general type which have been previously described and have their lower edges 326 slightly spaced from the ground surface 328 during normal operation, for restrained escape of air from said air cushions between the lower edges 326 and the ground surface 328.

For this purpose, an upper panel 330 may be substantially rectangular in shape and has side wall panels 332 and 334. A lower panel 336 extends from the side walls 332 and 334

completely across the plenum chamber 338. It is substantially the same size as the upper panel 330, except for the thickness of the side walls 332 and 334. It has openings 340, 342, 344, and 346. The openings 340 and 342 are substantially circular in horizontal extent, except where they are interrupted by the side walls 332. The openings 344 and 346 are circular in shape. Crossbars 350 and 352 span all of these openings and support rings 354 and 356 of the same nature as the inside wall supporting rings heretofore described, such as the ring 71 of FIGS. 1 to 3. The curtains have their outer walls 358 secured near the bottom of the plenum chamber, at the edges of the openings 340, 342, 344, and 346. However, where the larger curtains extend out beyond the sidewalls 332, a panel 370 is supported by the side walls of 332 by brackets or the like, so that the panel may support the upper ends of the curtain walls 358 at 372. The inner slanting walls 374 of the curtains are attached at 376 to the rings 354, 356. This construction provides a main supporting member from which the said curtains are supported to provide a plurality of air cushions of the character heretofore described.

A plurality of skids 380 may be supported at the corners of the plenum chamber 338 and may extend a sufficient distance below the bottom of the plane plenum chamber, as shown in FIG. 23. If desired, they may be slightly rounded at 382. When the operation of the blowing means 302 is stopped, the curtain constructions deflate and the craft settles down on the skids 380. The curtain constructions fold as indicated at 384 in FIG. 24.

If desired, the plenum chamber 338 may be made longer than illustrated, so the side walls 332 extend beyond the entire extent of the large curtains. In such a construction the panel 370 may be omitted, and the lower panel 336 may have complete openings 340 and 342 for the large curtains without interruption of the side walls 332.

FIG. 25 shows an embodiment somewhat similar to that disclosed in FIG. 12, which is referred to hereafter as representative of the group of FIGS. 11—20. All of the parts which are not specifically described as being different from FIG. 12 group may be similar to or exactly the same as disclosed in such FIG. 12 group.

The cockpit 400 may be substantially the same as that disclosed in the FIG. 12 group except that the engines 402 are placed inside of the cockpit 400, with partitions 404 separating the engines 402 from the passenger compartment. Suitable shaft seals, or stuffing boxes 406, may be provided where the shafts 408 pass through the end wall 410 of the cockpit. The fans or blower means 412, vanes 414 and 416, rudders 418, and curtain 420, may be substantially the same as the corresponding members illustrated and described in connection with the FIG. 12 group.

If desired, suitable drains 422 may drain the floor of the cockpit 400. These drains may be pipes open to the floor of the cockpit which extend radially outward through the solid side wall of the plenum chamber. This permits any water from rain, wave action, etc., to drain out of the cockpit at atmospheric pressure, both at the inlet and the outlet.

Suitable clutches 424 may be provided for engines 402 and their respective drive shafts 408. This permits the engines 402 to be started in unclutched condition so the load may be placed on the craft, and occupants may take their positions before the clutches 424 are actuated to drive the shafts 408.

The two clutches 424 may be controlled to clutch and declutch by any desired means. For example, these clutches 424 may be provided with control means which cause the two clutches 424 to be simultaneously clutched or simultaneously declutched. Also, the control means may be such that the clutches 424 may be independently clutched and declutched, so that the action of the fans 412 may be different from each other for any desired purpose, such as that previously described in connection with the FIG. 12 group. If desired, the clutches 424 may include variable transmissions, to permit the shafts 408, to be driven at different ratios under the actuation of such controls, to produce the effects previously described

in connection with the FIG. 12 group, or for any other purpose.

These controls of the clutches 424 may be electrical with solenoid action, or mechanical, with suitable linkages, and the like. Preferably all of these controls are within easy reach of the operator sitting in the seat 426. Such controls are diagrammatically represented by the line 430, together with the two vertical lines 432 and 434. These lines are emblematic of any suitable control to attain the results as described. The line 430 includes a sleeve 430a telescoping with a plunger 430b and a key 430c. When the key is tight, the clutches operate together and when the key is loose the clutches operate separately. Movement of the linkage 430, 432 and 434 to the right may produce clutching in both clutches, and movement to the left of the linkage 430, 432 and 434 may produce declutching, for example.

In this connection, it is to be understood that similar clutches and controls may be provided for the engine drives in all of the embodiments herein disclosed. Such clutches permit the engines to be idled at any desired time for any desired purpose.

In the embodiment of FIG. 25, the engines 402 have their air intakes, and their exhausts, both connected to the surrounding atmosphere 436, so the engines operate at normal atmospheric pressure at all times.

FIG. 26 shows an embodiment in which a plurality of units 440, 442, 444, and 446 are connected together by flexible connections 448 so the entire caravan, or "train", travels together for transportation over land and/or water.

The units 440, 442, 444, and 446 may be similar to any of the units herein disclosed. They may be all alike or different from each other, as desired. Any number of units may be so connected.

The connections 448 may be any connections, tubular or not, as desired, which join the units together merely for the purpose of maintaining them as a single "train". If desired, however, the connections 448 may be tubular air conduits, as well as pulling members. The outward appearance of the conduits or rope-like connectors 448 is the same, as illustrated. This permits the air from the plenum chamber of unit 440 to flow through such connections 448 to the various plenum chambers of units 442, 444, and 446 with sufficient ease so each unit is provided with superatmospheric air without the necessity of individual blowing means on each unit. For example, the unit 440 may be one which may be substantially similar to that shown in FIGS. 12 or 25, and the capacity of the blowers in these units may be sufficient so air can be supplied from the plenum chamber, or from an auxiliary blower, through the connections 448 to the various plenum chambers of units 442, 444, and 446. Alternatively, the connections 448 may be merely for pulling purposes, and supplemental air conduits may be provided between the various units. Alternatively, each of the units 440, 442, 444, and 446 may have individual blowing means, such as shown in FIGS. 1—5, for example, and may be controlled by an operator on each individual unit. Alternatively, each unit 440, 442, 444, and 446 may have individual airblowing means and other controls as previously described in connection with all of the embodiments herein disclosed. A master control for all of these features may be provided on one of the units, such as the unit 440, by "actuators" for distant control, as elsewhere described. These are conventional and well known and hence are not illustrated to avoid superfluous drawings.

Such a "train" may travel over rough terrain, both over land and over water and over relatively high objects without the necessity of roads, bridges, and the like.

FIG. 28 shows a feature which may be added to the FIG. 12 group. For example, a substantially hermetically sealed door or removable cover 450 may be secured by fastening means 452, which may have hinges, latches, etc., so the door or cover 450 may be opened for servicing the engines 454 or for cranking the same, etc. The engines 454 may be supported from the top panel 458 by any suitable means, such as supports 459, to

permit access through the opening 456, and to permit the door or cover 450 to be opened. The intakes and exhausts of the engines 454 may be connected through the side wall of the plenum chamber with the outside atmosphere, if desired in a manner substantially similar to the intake conduit 660 and exhaust conduit 662 constructions shown in FIGS. 34-36 and described more fully hereinafter by reference thereto. The remainder of the embodiment may be substantially identical with that disclosed in connection with the FIG. 12 group.

FIG. 30 is a vertical view of another embodiment. Two or more blowing means or fans 460 may be rotated by engines 462. The engines 462, with suitable clutch controls, drive the blowers 460, force air from the surrounding atmosphere 464 through the openings 466 into the space 468 of the curtain construction 470, and into the space 472. The action of the curtain is substantially the same as in any of the embodiments of FIGS. 1 to 9. The location of the blowers 460 is chosen so the air is distributed throughout the spaces 468, 472 and 474, and the air may travel freely in and between each of these spaces 468, 472 and 474.

Means 480 may be provided centrally of the unit to receive and hold any load desired, such as a "dead" load or a passenger load. For example, the means 480 may take the form of a pad or beam which may extend completely across the entire top of the unit of FIG. 30, or it may be a central pad only. Such means 480 may support a column, beam, box, or any other type of load illustrated generally at 482.

In connection with the embodiment of FIG. 30, as well as with any other of the other embodiments herein disclosed, the superatmospheric air which is to be supplied within the unit may be supplied by a separate air pump which need not be supported by the unit. For example, as shown diagrammatically in FIG. 30A a separate cart 475 may include an engine 477 and air blower 479, connected by air conduits 481 to the plenum chamber 474 or any other part of the unit.

A master air supply may be provided on a separate cart, as previously described, and this separate air supply may have a plurality of air ducts leading to a plurality of several units, such as that shown in FIG. 30, which units need not have the engines and blowers 462 and 460 respectively, and in which no air openings are provided where such fans 460 are illustrated. However, controls producing sidewise motion, etc., may be included in such units, and they may be of the character disclosed in FIG. 4.

In this manner, a very heavy load may be lifted by a plurality of these units which may be placed under columns or beams while the units are in uninflated condition. After all of the units have been properly placed under the heavy load, these units may then be inflated from the master air supply, if desired, and then the entire load and units are lifted a slight amount above the ground surface and they may be moved in unison to another place. Alternatively, each of the units may be provided with fans 460 and engines 462 under a master control, to control the clutches and/or the engines, as desired. Likewise, the controls for sidewise motion of the character disclosed in FIG. 4 may be under the control of a single master control, if desired.

FIG. 31 is a partial plan view of FIG. 30. In this case, the means 480 may be a central pad or cockpit. If it is a cockpit, it may be provided with a seat 484 and a control stick 486 of the character disclosed in the groups of FIGS. 12 and 25. The engines 462 and the blowers 460 introduce air from the surrounding atmosphere through the openings 466 into the spaces 468, 472, and 474, by proper location and distribution, as is obvious. Suitable exhausts 488 may be provided from the plenum chamber 474. These exhausts may have any of the features disclosed in connection with FIG. 4 to produce sidewise motion, tilting motion, turning motion, etc. If desired, it may also have the additional fan or blower for lateral movement.

The engines 462 of FIGS. 30 and 31 may be gasoline engines of the type which are used with vertical shafts to rotate horizontally disposed blades of grass cutters, and the like. Such engines, now on the market, are provided with suitable

fuel tanks, throttle controls, etc., and with clutches which may be clutched or declutched, as desired. All of these controls may be actuated by a single person by a unitary control, if desired.

FIG. 27 shows an embodiment in which a circular or columnar space 500 may be substantially hermetically sealed from the central part 502 of the air cushion. The columnar space 500 may be enclosed within a curtain 504 which may include an outer wall 506 secured and sealed at 510 to platform sidewall 516, and an inner wall 508, secured and sealed at 512 to the platform 514. If desired, the rigid side wall 516 may extend around the unit, but, if desired, the outer, flexible wall 506 may continue, without such a side wall 516, to the platform surface 514.

The space 500 may be supplied with air at superatmospheric pressure by one or more air-blowing means 518, which may be air fans or blowers. Air from the surrounding atmosphere 520 is drawn by the blowers 518 through the openings 522 and is discharged at superatmospheric pressure into the space 500. The fan or fans 518 may be individually driven by their own engines, not shown. Alternatively, such blowers may be provided with pulleys 524, and they may be driven by belts 526 and 528 from a master pulley 530, which is driven by the engine 532. The engine drives, through a suitable clutch 533, similar to the clutches 424 noted earlier with reference to FIG. 25, the pulley 530 and the vertical shaft 534, which is connected to the fan or blower 536. The blower 536 withdraws air from the surrounding atmosphere 520 and discharges it through the opening 538 into the air cushion 502, while the blowers 518 simultaneously discharge air into the space 500.

The pressure in the space 500 may be substantially the same, or merely slightly more than the pressure of the air cushion 502. The air from the space 502 passes under curtain 504 through the narrow passageway or space 540 to the surrounding atmosphere 520. The Venturi action produced at this point, as previously described, aids in maintaining the bend 542 or bottom edge of the curtain at its lowest possible position in a manner somewhat similar to that previously described in connection with other embodiments.

Suitable skids 544, with or without wheels and brakes, as previously described, may be provided. Such skids may be terminated at the point 546, sufficiently low to prevent the platform 514 and sidewall 516 of the embodiment from striking the ground. Alternatively, such skids may extend to a lower point 548 substantially even with the bend 542. In either case, such skids may be made retractable in the same manner as illustrated in FIG. 29, so that the apparatus may glide over relatively high objects without impact.

The air-blowing means or blowers 518 may be so powered that they automatically stop when the air introducing means 536 stops. They automatically start when the air-blowing means or introducing means 536 starts. This may be automatically accomplished by the belts 526 and 528. If engines are provided for the fans 518, these are made to be started and stopped substantially with the blower 536.

Under certain conditions, the inner wall 508 may be provided with openings 550 which are shown in FIG. 27A. These openings are sufficiently small, so they maintain a slightly greater pressure in the space 500 than in space 502. The difference in pressures may be regulated by the size of the openings 550. They are chosen, so that they produce a slight restriction of flow to insure the slightly higher pressure in 500 than in 502. However, under other conditions, these opening 550 may be omitted.

In the embodiment of FIG. 29, the spaces 500a and 502a may be substantially the same as in FIG. 27. The skids 544a may be substantially the same as skids 544 of FIG. 27. Raising and lowering means 560 may be hinged to the skids 544a and to the top or platform surface 514a, for raising and lowering the skids. Similar constructions may be provided for the embodiment of FIGS. 27 and 27A. The engine 532a and blower 536a, and air opening 538a, may be substantially the same as disclosed in FIG. 27. However, the air or other gaseous medi-

um which is to be introduced into the space 500a may be supplied through a pipe 562 under the control of a valve 564 which has a manual control 566. Such a control 566 may open and close the valve. In addition, the valve 564 may be a pressure-reducing valve which automatically supplies the gaseous medium into the space 500a at the desired maximum pressure but stops supplying such gaseous medium after such pressure is attained in the space 500a. Such a valve is well known and is generally referred to as a constant pressure discharge valve in which the valve will not discharge the medium at any greater pressure than that for which the valve is set.

In operation of the embodiments of FIGS. 27 and 27A, the load is properly placed on the craft while the space 500 is completely deflated in FIGS. 27 and 27A, and the craft is resting on the skids 546 or 548. Then the engine 532 is started, and it simultaneously causes inflation of the spaces 500 and 502, so that the craft quickly rises to the normal operating condition and may be moved about as previously described in connection with all other embodiments under the various controls heretofore described for sidewise, tilting and other movements as is evident. In the embodiment of FIG. 29, the craft is supported on the skids 544a with the space 500a inflated or deflated. After the load has been properly placed on the craft, the space 500a is inflated, if it has not previously been so inflated.

After the space 500a has been inflated to the desired or necessary pressure, then the engine 532a may be started and the air cushion 502a may be inflated to the normal operating pressure of the character herein and elsewhere specified. Proper controls of the characters herein and elsewhere described may be provided to produce sidewise tilting, and other movements or conditions of any desired character.

The skids 544a preferably are in the lowered condition, as shown in solid lines in FIG. 29, before the space 502a is deflated. The space 500a preferably is inflated to the desired condition before the space 502a is inflated for normal operation.

The features of FIGS. 27, 27A and 29 may be applied to any of the embodiments elsewhere herein disclosed.

FIGS. 34-36 show an embodiment which resists substantial tilting of the lifting device, vehicle, toy, etc., even when unevenly loaded. This is accomplished by providing a main supporting member from which a plurality of curtains depend and to which they are sealed. The curtains may be of the type disclosed in the previous figures such as in FIGS. 1-5 and/or 21-24 etc.

The curtains may be of substantially the same size with respect to each other. They may be supported in such a manner that each curtain has a substantially independent air cushion associated with such respective curtain. Superatmospheric pressure air may be supplied to each such independent air cushion in a manner to maintain a proper supply of superatmospheric air to each such cushion.

Because of the constructions of this embodiment, a load, such as a passenger load, or freight load, may be placed on the supporting member of such embodiment a substantial distance from the center of the supporting member without causing any substantial tilting of the supporting member.

This is accomplished because each separate curtain and air cushion associated therewith is capable of sustaining a substantial load independently of the other curtains and air cushions.

Suitable directional controls are provided, such as air jets, blowers, fans and the like to guide and propel the device.

Referring now specifically to FIGS. 34, 35 and 36 there is shown an embodiment of the present invention in which a plurality of curtains, such as the four curtains 602, 604, 606, 608, are sealed to and depend from the relatively rigid supporting member 610. Each of the curtains 602, 604, 606 and 608 may be made of thin, flexible, air impermeable, relatively non-stretchable material which is relatively non-self-supporting in an edgewise direction such as previously disclosed. Each of these curtains may be substantially the same in character and

construction as the curtains disclosed in connection with FIGS. 1-5, 21-24 and the similar curtains disclosed in connection with other figures of this application.

If desired the curtains 602, 604, 606 and 608 may be substantially of the same size with respect to each other.

The operation of each of these curtains 602, 604, 606 and 608 with respect to the "ground" surface 612 may be substantially the same as that of curtain 54 of FIGS. 1-5, and similar curtains in FIGS. 21-24, and of the similar curtains shown in other figures. That is, in normal operation, the lower intermediate peripheries or edges or bends 614 of curtains 602, 604, 606 and 608 are lifted a relatively narrow peripheral distance or space 616 above the "ground" surface 612 to permit a limited outward flow of superatmospheric pressure air to the surrounding atmosphere from each of the respective air cushions with which the curtains 602, 604, 606, 608 are associated.

The supporting member 610 may enclose a plurality of sub-plenum chambers 618, 620, 622 and 624 which constitute a composite plenum chamber encompassed by any suitable type of supporting member 610, which, for example may have the upper and lower relatively rigid, substantially horizontal members 626 and 628 which are connected and sealed to a vertically directed peripheral wall 630 to encompass the composite plenum chamber.

The composite plenum chamber may be subdivided into sub-plenum chambers 618, 620, 622 and 624 by baffle structures 632 and 634 which may extend in a general vertical direction between the horizontal members 626 and 628 to isolate the sub-plenum chambers 618, 620, 622 and 624.

Air introducing means may be provided to introduce air at superatmospheric pressure into each of the curtains 602, 604, 606 and 608 in a manner to produce substantially independent air cushions surrounded in part by each of said curtains to lift the supporting member and to lift the respective lower edges 614 of said curtains a relatively narrow distance 616 above the "ground" surface 612. The construction is such that it resists any substantial tilting action of the supporting member 610 when subjected to off center load conditions.

Such air introducing means may take the form of a vertical shaft air fan or blower 636 driven by an engine 638 to withdraw air from the surrounding atmosphere through the intake opening 640 and deliver it at superatmospheric pressure into the fan chamber 642. This superatmospheric air may be delivered independently through the conduits 644 and 646 into the sub-plenum chambers 618, 620, 622 and 624 and into the curtains 602, 604, 606 and 608 to produce substantially independent air cushions surrounded in part by each of the curtains 602, 604, 606 and 608.

The curtains 602, 604, 606 and 608 each have substantially vertical cylindrical outer walls 648 corresponding to walls 358 of FIGS. 21-24 and slanting inner walls 650 corresponding to walls 374 of FIGS. 21-24 joined at their bottoms by bends 614 corresponding to bends 326 of FIGS. 21-24. The bends 614 are downward pulling means at the lower edges of the respective curtains 602, 604, 606 and 608 to produce a downward pull on each of said curtains.

The curtains 602, 604, 606 and 608 may be supported from the relatively rigid lower platform or horizontal member 628. This member 628 may have four openings 652 which may be circular, to which the upper ends of the vertical outer curtain walls 648 are sealed and secured. Cross pieces 654 and 656 may bridge the openings 652 and support rings 658 to which the upper ends of the slanting inner curtain walls 650 are attached.

As best seen in FIG. 34, the curtains 602, 604, 606 and 608 may have their outer walls 648 spaced from each other a sufficient distance at 651 to permit a free exit of air outwardly between the outer walls 648 from the central part of the lifting device after such air has been discharged from the air cushions past the spaces 616. Similar spacing is provided in FIGS. 37-54.

The engine 638 may be of any desired type, such as a vertical shaft gasoline engine having an air intake for combustion of the fuel wherever desired, such as through conduit 660 extending from the outside atmosphere through wall 630. The engine 638 may have an exhaust for the products of combustion through conduit 662 which may extend from the engine 638 to the outside atmosphere through wall 630.

Directional and propelling controllers or forces may be provided for the lifting device. For example, jets 664 may have their discharge outlets 666 horizontally directed, and may have their vertical inlets 668 connected with a suitable source of air under superatmospheric pressure, such as connected respectively to the sub-plenum chambers 620 and 624. Suitable valves 670 may be provided to regulate the amount of discharge of air which may leave the jets. These jets 664 may be rotatable about their vertical axes to direct the outlets 666 to other positions, such as those shown in dotted lines in FIG. 34. In this manner the reaction to the jet discharge may be used to propel the lifting device and to guide it directionally in any desired direction.

Additionally, or alternatively, other directional and propelling controller forces may be provided. To this end, four jets 674 may be provided for forward, sidewise and backward propulsion and may be mounted to be rotationally movable about their vertical axis or mounts so that the directional or propelling forces produced at their discharge outlets 666 may be directed in any desired direction by rotation about their vertical axis.

If desired a directional or rudder-like jet 675 may be provided at the rear end of the vehicle which provides a turning movement of the vehicle similar to that provided by a rudder of a ship.

The jets 674 and 675 may be supplied with air under pressure up through their vertical inlets from the sub-plenum chambers 618, 620, 622, and 624, or from separate blowers and motors, for example as shown in FIG. 45.

The jets 664, 674, and 675 may be rotated about their vertical axes by any well-known actuators and actuating means, such as the motors with controllers spaced therefrom by cables to the desired controlling location. The actuators may be hydraulic, cable or any other desired type which are well known in the art of actuators. All of the other directional controllers and propulsion controllers may be controlled by actuators of the same type such as those used to lift windows in automobiles by the actuation of a switch which is spaced from the window, etc.

The controllers or jets 664, 674, and 675 may be used simultaneously when extra power is required or desired or when the guidance of the lifting device requires both in cooperation. They may also be used sequentially to each other as a different location is approached where one type of controller is not desirable but the other type may be used. The same is true of all other controllers which are disclosed in this application.

The directional air propulsion controllers or jets 664, 674 and 675 may be applied to any of the embodiments herein disclosed.

Passenger compartments 678 and 680 may be provided. Under certain circumstances the compartment 680 may be omitted. Either or both of the compartments 678 and 680 may be produced by providing a side wall construction 682 and bottom wall construction 684. If desired, a seat 686 may be provided on which one or more passengers may sit. A controlling lever 688 is emblematic of any number of controlling devices which may be placed in the compartment 678 for controlling the propelling and guiding devices, etc., of the lifting device.

A plurality of skids 690 may be provided for supporting the lifting device when the curtains are deflated by the stopping of the superatmospheric air supply or blower 636. The members 690 may be vertical plank-like members and may have rounded or curved feet or skids or wheels, of which the rounded, dotted line 692 is emblematic.

FIGS. 37 and 38 show an embodiment somewhat similar to that disclosed in connection with FIGS. 34, 35, and 36. The embodiment of FIGS. 37 and 38 may have curtains 700, 702, 704, and 706 which may be substantially identical with the curtains 602, 604, 606, and 608 of FIGS. 34 to 36. The supporting member 708 may generally be the same as the member 610, including baffles 710, which may be similar to baffles 632. However, the inner ends 712 of the baffles 710 terminate against a pressure chamber 714, which has restricted passageways 716, which discharge into the sub-plenum chambers 718. The sub-plenum chambers 718 may be substantially the same as the sub-plenum chambers 618, 620, 622 and 624 of FIGS. 34 to 36. A suitable engine 720, similar to the engine 638, and a blower or fan 722 similar to fan 636 may be connected by the vertical shaft 724 to cause air from the atmosphere to be propelled by the fan 722 into the pressure chamber 714 to provide air under superatmospheric pressure in such chamber 714. From thence the superatmospheric pressure air is discharged through the restricted outlets 716 into each of the sub-plenum chambers 718 which are above the curtains 700, 702, 704, and 706 respectively. All of the details of FIGS. 34, 35 and 36, which are not shown in FIGS. 37 and 38 but which are applicable thereto may be incorporated in FIGS. 37 and 38, including the directional and propulsion controllers or jets 664, 674 and 675.

FIGS. 39 and 40 show an embodiment somewhat similar to that of FIGS. 34 to 38. In FIGS. 39 and 40, the sub-plenum chambers 730 and the supporting member 732 and baffles 734 may be substantially the same as corresponding members in FIGS. 34 to 38. However, in lieu of the single pressure chamber 642 of FIGS. 34 to 36, or the single pressure chamber 714 of FIGS. 37 and 38, individual motors or engines 736, and individual fans or blowers 738 may be provided to feed superatmospheric pressure air from the atmosphere through the inlets 740 directly into the sub-plenum chambers 730 which are located directly above the curtains 742. Likewise, the curtains 742 may be substantially the same as described in connection with FIGS. 34 to 38 inclusive. The central baffle 744 may be substantially the same as the baffle 634 of FIGS. 34 to 36, which, however, does not have the pressure chamber 642 to interrupt the continuity of the baffle 744. All of the features disclosed in connection with FIGS. 34 to 38 are applicable to FIGS. 39 and 40, including the directional and propulsion controllers or jets 664, 674, and 675.

FIGS. 41 and 42 show an embodiment somewhat similar to the embodiments disclosed in FIGS. 34 and 40 inclusive. However, in FIGS. 41 and 42, two blowers 750 and 752 are driven by the engines 754 and 756 respectively by the vertical shafts 758. The blowers 750 and 752 have air inlets 760 and discharge outlets 762 to discharge air under superatmospheric pressure into the sub-plenum chambers 764, which sub-plenum chambers 764 are directly over the curtains 766 which are supported by the support member 768. The plenum chambers 764 are separated by the baffles 770 and 772. All of the details of FIGS. 34 to 40, which are applicable to FIGS. 41 and 42, may be incorporated in such FIGS. 41 and 42, including directional and propulsion controllers or jets 664, 674, and 675, as is obvious. Corresponding members may be as identical as possible.

FIG. 43 is a plan view of an embodiment in which three sub-plenum chambers 772 may be located above three curtain constructions 774. In this case the outer wall 776 of the supporting member corresponding to supporting member 610 may be circular, and the baffles 775 separate the corresponding sub-plenum chambers 772 from each other at the supporting member. An air pressure chamber 778 is substantially the same as the air pressure chamber 642 of FIGS. 34 to 36 and may have an air intake 780. A fan or blower and engine (not shown) corresponding to fan 636 and blower 638 of FIGS. 34 to 36, may be provided in the chamber 778. Restricted conduits or orifices 782 permit air under superatmospheric pressure to be discharged from the chamber 778 into the respec-

tive sub-plenum chambers 772 which are directly above curtain structures which are substantially the same as curtain structures 602, 604 and 606. However, curtain structures of FIG. 43 may be located to have their central vertical axis located at the corners of an equilateral triangle. All of the features of FIGS. 34-42 which are applicable may be applied to the embodiment of FIG. 43.

FIG. 44 is a top plan view showing an embodiment of the present invention in which an elongated outer wall 782 encompasses the sub-plenum chambers 784, of which there are six such plenum chambers 784. These plenum chambers are separated by baffles 786. Two air pressure chambers 788 may be substantially the same as the pressure chamber 778 of FIG. 43 and may have restricted discharge outlets 790 into the sub-plenum chambers 784. Each pressure chamber 778 discharges into three sub-plenum chambers 784. Each sub-plenum chamber 784 may be directly above the corresponding curtain constructions 792 which may be substantially identical with the curtain constructions 602, 604, 606, etc. of FIGS. 34 to 36 inclusive. All of the features of FIGS. 34-43, including the directional and propulsion controllers or jets 606, 674 and 675, may be included in the embodiment of FIG. 44.

FIG. 45 is emblematic of a jet construction which may be applied to all of the embodiments herein disclosed. In this embodiment, the space 800 is emblematic of any of the plenum or sub-plenum chambers herein disclosed in any of the modifications. Any number of jet constructions 802 may be L-shaped in the same manner as the jet constructions 664 of FIGS. 34 to 36 inclusive. The outlets 804 may be horizontally disposed as indicated in dotted lines. The jet construction may be provided with valves 806 to regulate the discharge into the atmosphere. The inlet ends 808 may be sealed either by a permanent closure, or by a valve construction as indicated at 810, so such opening 808 may be opened or closed as desired. Normally the opening 808 is maintained closed by valve 810 except when it may not be convenient or desirable to operate the fan or blower 812. An additional blower 812 has its intake 814 connected to the atmosphere outside of the lifting device and has two outlets 816 which deliver air at superatmospheric pressure into the jet constructions 802.

The blower or fan 812 may be driven by an engine 820. The jets 802 may be rotated about their vertical axes by actuators of the type herein elsewhere described and which are of well known applicability for turning the jets 802 about their vertical axes and hence are not further described in connection with this figure.

By the construction of FIG. 45, the jet action of the jet 802 may be of any desired magnitude or adjustment independent of the pressures and volumes which are prevalent in the sub-plenum chambers or in the regular plenum chambers of any and all modifications and embodiments herein disclosed. Hence air may be supplied to the jets 802 at a higher pressure by the fan 812 than the pressure in the plenum chamber 800.

FIGS. 46 and 47 are diagrammatic horizontal and vertical views of one embodiment of an actuator system specifically for the propulsion and directional controllers 664, 674 and 675 of FIGS. 34-36, but are applicable to any similar propulsion and directional controller systems herein disclosed.

For example, in FIGS. 46 and 47, the jets, blowers, etc., 664 and/or 674 may be controlled by a hand operable steering wheel 830, and, if desired, such jets or blowers 664 and/or 674 may be simultaneously turned to other angular positions by wheel 830. They may be turned into other parallel positions if desired. The directional and propulsion controller, or jet, blower, etc. 675, may be controlled by foot operated pedals 832 and 834 so such controller 675 may be turned angularly in any desired direction.

If desired, the controllers, such as the jets, blowers, etc., 664 and 674 may be used to give the vehicle a course substantially in line with the stem to stern axis 844 by placing the controllers 664 and 674 parallel to such axis, as indicated by solid arrows 836. When a sidewise drift is desired, without substantially deviating the stem to stern axis from a course parallel

with the original course, the controllers 664 and/or 674 may be turned in unison by the steering wheel 830 to selected angles, as indicated by the dotted arrows 838. Such adjustment also may be used to neutralize any sidewise drift which might be caused by a sidewise wind or sidewise slant in the road, so the vehicle may be maintained in a straight course.

The controller, such as a jet, blower, etc., 675 may produce a rudder-like action for the purpose of turning the vehicle stem to stern axis away from its original course, and at an angle to such course. The controller 675 may be turned by operation of the pedals 832 and 834. Forward movement of the pedal 832 causes the controller 675 to turn to some position in the nature of the dotted line arrow 840, and away from its normal position which is indicated by the solid arrow 842 and by the full line showing of the member 675. Such movement to arrow position 840 or the like causes the stem to stern axis 844 to change to some other course, such as indicated by the dotted line 846. Forward movement of the pedal 834 causes the course to be changed to the other side of the full line position of FIG. 46, as is obvious.

Any actuating system may be used to cause the wheel 830 to move the controllers 664 and/or 674. Likewise, any type of actuator may be used to cause the pedals 832 and 834 to move the controller 675 as heretofore described. By way of example, the wheel 830 may rotate a shaft 848, which in turn rotates the pulley 850. The pulley 850 may actuate a chain, cable, or the like, 852, or a group of such cables, which in turn actuate the pulleys 854, all of which may be of the same diameter as the pulley 850. As best seen in FIG. 47 the pulleys 854 are connected to the vertical funnels, or shafts, or the like, 856, to turn the controllers 664 and 674 in a manner corresponding to the movement of the wheel 830. While the pulley 850 has been indicated to be of the same diameter as the pulleys 854, it is to be understood that the pulley 850 may be smaller or larger than the pulleys 854, to provide a leverage increase or decrease of turning movement, as desired. The cable connections between the steering wheel 830 and the blowers 664 and 674 may be changed as desired.

The pedals 832 and 834 may be carried by a bar 860, which is connected to a vertical shaft 862, which in turn is connected to another bar 864, which may be similar and of the same size as bar 860. The ends of the bar 864 may be connected to chains or cables 866 and 868 which cross each other and are connected to a bar 870, which is attached to the vertical funnel or shaft 872 for turning the controller 675 in the manner elsewhere described. While the bars 864 and 870 are shown to be of a given ratio, any other ratio may be used to produce more or less relative movement of the controller 875 in comparison to the movement of the pedals 832 and 834, as is obvious.

FIG. 48 is a view similar to FIG. 46, but shows an electrical system for actuating the controllers 664, 674, and 675. The controllers 664, 674, and 675 may be substantially identical with those disclosed in FIGS. 46 and 47, except that the vertical funnels or shafts 856 and 872 may be provided with worm gear wheels 870, which are engaged by the worm drives 872. Reversible motors 874, 876, and 878 may drive the worms 872 to turn the controllers 674, 664, and 675 to the various positions described in connection with FIGS. 46 and 47. The motors 874 and 876 and 878 may be controlled by any type of switch construction 880, which is capable of driving the motors to any desired position of the controllers. Suitable electric cable constructions 882 may lead from the switch construction 880 to the various motors. The electrical system may be energized from a battery and/or a generator in a well-known manner. The switch construction 880 may be such that it can place any one of the controllers 664, 674, and 675 at any desired angle independently of each other, as by individual control levers, or to have the unison movement of the controllers 664 and 674 of FIGS. 46 and 47, with the independent movement of the controller 675. Electrical systems of this character are well known and hence are not further described.

FIG. 49 shows a construction similar to that of FIGS. 46 and 48, except that blowers 884 and motors 886 are mounted on the deck of the vehicle to swing about the vertical shafts or swinging pivots 888. These motors and blowers may be controlled by any type of actuating system, such as that disclosed in FIGS. 46, 47, and 48, or any other desired actuating system, to produce the vehicle movements described in connection with FIGS. 46 and 48, or any other movements desired. Any number of blowers 884 and motors 886 may be provided for each vehicle, as is obvious.

The solid line arrows 890 of FIG. 49 indicate the normal position of the blowers 884, and such normal position produces a straight forward stem to stern axial movement of the vehicle, as indicated by the solid arrow 892. If the blowers are turned to the dotted arrow positions 894 and 896, then the vehicle has a slight stem to stern sidewise drift movement, and also a turning movement to produce a motion somewhat similar to that indicated by the dotted arrow 898. Other movements of the vehicle may be produced, as is obvious.

In the embodiment of FIGS. 50-54, an oval vertical peripheral wall 900 has a flat upper cover 902 and a flat lower floor 904 which may be flat, sheet-like oval members attached at their peripheries to the upper and lower edges of the oval wall 900. The top wall or cover 902 is omitted in FIG. 50, but is shown in FIG. 54.

Four flexible, cylindraceous curtains of the type heretofore described are mounted below the wall or floor 904. The top edges of the outer walls of the curtains (corresponding to wall 62 of FIG. 2, etc.) are indicated by the circles 906, 907, 908 and 909 in FIG. 50. The top edges of the inner inclined portions of the curtains (corresponding to inclined wall 68 of FIG. 2, etc.) are indicated by the circles 910, 911, 912, and 913 in FIG. 50. The circles 906-909 also indicate the periphery of openings, or partial openings, in floor 904 for downward passage of superatmospheric air.

A set of vertical curtain supporting rings or circular bands extend downwardly from the wall or floor 904 a slight distance to support the upper edges of the curtain walls. For example, a ring or band 914, FIG. 51, supports the upper outer edge 906 of one curtain. A concentric inner ring or band 916 supports the upper inner edge 910 of the inner inclined portions of another curtain. As best seen in FIG. 51, another outer ring 918 and an inner concentric ring 920 extend downwardly from the floor 904 to support respectively the upper edges 908 and 912 of another curtain. Another outer ring 922, FIG. 52, and an inner concentric ring 924 support respectively the upper edges 907 and 911 of another curtain. Another outer ring 926 and an inner concentric ring 928 support respectively the upper edges 909 and 913 of another curtain. The vertical height of bands or rings 914, 916, 918, 920, 922, 924, 926 and 928 may be decreased or increased to any relative proportion, as desired, and may be substantially zero, if desired.

In normal operation these curtains hang down and have ring-shaped channels or joints 930 (corresponding to 66 of FIG. 2) which are spaced a small distance above the ground surface 932 in a manner similar to the other curtains elsewhere described herein.

As best seen in FIG. 50 the embodiment of the invention illustrated therein is provided with supporting legs 1030 which are of a construction similar to the skids 76 heretofore described by particular reference to FIGS. 1 and 3. Of course, other skid constructions or supporting wheel arrangements, such as the wheels 76J described earlier by reference to FIG. 5 can be employed if desired.

The floor 904 has openings substantially of the same size as the outer rings 914, 918, 922, and 926. These openings permit air under pressure to enter into the annular curtain spaces 934 (corresponding to 38 of FIG. 2) within all four curtains, and into the core spaces 936 (corresponding to 34 of FIG. 2) which are surrounded by the inner walls of all four curtains.

A substantially rectangular box 939, FIG. 50 is provided to contain passenger compartments, engine and blower compartments, etc., and has end walls 940 and 942 and side walls 944

and 946. The box side and end walls are supported on the floor 904 and within the oval outer wall 900.

A plurality of vertical baffles 948, 950, 952, and 954 extend upwardly from the floor 904 up to the cover 902. They also extend diagonally outward from the side walls 944 and 946 of the central box 939 to the oblong outer wall 900.

The construction is such that two blowers 956 and 958, of a generally squirrel cage type, with horizontal drive shafts receive air respectively from the grilles openings 960 and 962, FIG. 54, and chambers 964 and 966 respectively which are under the grilles openings 960 and 962. As best seen in FIGS. 51 and 53, the blower 956 has an intake at 968 and has a discharge at a divided opening 970, 972, FIG. 53, which discharges air under superatmospheric pressure into the sub-plenum chambers 974 and 976 respectively. The blower 958 has an air intake at 978 and has a discharge through a divided opening 980, 982 which discharges into the sub-plenum chambers 984 and 986 respectively.

As best seen in FIGS. 50 and 51, the central box 939 has a combined luggage and fuel tank compartment 988 between walls 942 and 989, an air intake compartment 964 between walls 989 and 965 a compartment 957 in which the blower 956 is contained, a rear seat compartment with seat 1024, a motor compartment or tunnel which contains motors 1010 and 1012, a compartment in which the blower 958 is contained, the air intake compartment 966, and a front seat compartment containing seat 994.

The rear sub-plenum chamber 974 extends completely around the end wall 942 of the box 939, while the front end sub-plenum chamber 984 extends completely around the end wall 940 of the box 939. The side sub-plenum chamber 976 is bounded by the baffles 952 and 954, part of the box side 946, and part of the oblong outer wall 900. The side sub-plenum chamber 986 is bounded by the baffles 948, 950, by part of the box side 944, and by the oblong outer wall 900. The sub-plenum chamber 974 discharges superatmospheric air into the annular air spaces 934 of the curtain walls 908, 912, and into the core space 936 inside the inner curtain wall 912. The sub-plenum chamber 976 discharges superatmospheric air into the annular air space 934 of the curtain walls 909, 913, and into the core space 936 inside the inner curtain wall 913. The sub-plenum chamber 984 discharges superatmospheric air into the annular air space 934 of curtain walls 906, 910, and into the core space 936 inside the inner curtain wall 910. The sub-plenum chamber 986 discharges superatmospheric air into the annular air space 934 of curtain walls 907, 911, and into the core space inside the inner curtain wall 911.

Two propulsion and directional jets 1000 and 1002 are shown in FIG. 54. These jets may be of the type illustrated in FIGS. 47-49, which may be rotated about a vertical axis by any suitable means. For example, they may be rotatable by electric power of the character disclosed in FIG. 48, in which a motor 874, worm 872 and worm gear wheel 870 are used to rotate the jet about a vertical axis. Additionally, the jets 1000 and 1002 may be emblematic of any other type of propulsion means, such as the motor and blower type shown in FIG. 49, etc.

The jets 1000 and 1002, for example, may be driven by the motor and worm construction of FIG. 48. The jet 1000 may be controlled by a proper switch construction having a proportional rotatable switch arm 1005, FIG. 50, while the jet 1002 may be proportionally controlled by a switch construction having a similarly rotatable switch arm 1007. Actuator electric circuit constructions of well known construction may be used whereby rotation of the horizontal switch handle 1005 around an axis, as indicated by the dotted circular line 1009, proportionally moves the jet 1000 to any desired positions, similar to that of the handle 1005. For example, the jet 1000 may be moved from the position indicated by the solid line arrow 1000A to any one of the dotted line arrow positions indicated at 1000B-1000F inclusive, or any other desired position about the vertical axis of the jet 1000, by movement of switch handle 1005 to selected positions about the axis of the handle 1005.

Similarly, the jet 1002 may be moved by rotation of a similar switch construction controlled by the switch handle 1007 which is movable about the axis of handle 1007, as indicated by the dotted circle 1011, to produce any desired corresponding positions for the jet 1002, such as positions 1002A—1002F, inclusive, etc., in a manner similar to that described in connection with switch handle 1005 and jet 1000. As previously stated, the jets 1000 and 1002 may be emblematic of any other type of propulsion devices, which may be used in lieu of jets 1000 and 1002, such as two motors and blowers of FIG. 49.

The jets 1000 and 1002 preferably are positioned in the rear half (or the front half) of the vehicle, or in the median transverse axis of the vehicle so that they can produce not only a directional propulsion on the vehicle, but also a turning, stopping, slowing or speeding up movement, and an idling condition. For example, with these jets in positions 1000A and 1002A, a forward movement of the vehicle is produced along the stem to stern axis 1013. If the jets are moved to positions 1000B and 1000F, then a forward and leftward course is produced for the vehicle. If the jets are positioned at 1000B and 1002B, then a straight forward course is produced, but at a slower speed, since the jets expend part of their energy in producing opposed inward vectors, which dissipate some of the energy of the forward thrust and thus reduce the speed of the vehicle. To stop the forward movement of the vehicle, or to produce a backward movement of the vehicle, the jets may be moved to the positions 1000E and 1002E. A slower stopping movement or a slower backward movement may be produced by positioning the jets at 1000D and 1002D. An idling position of the jets is produced at positions 1000C and 1002C. Other movements may be produced by other positions of the jets, as is obvious.

This control of a vehicle by two jets, such as jets 1000 and 1002 may also be applied to and used in any of the other embodiments of this invention. Conversely, any of the propulsion and directional controls shown in connection with any of the other embodiments of this invention may be used with the embodiment of FIGS. 50 through 54 in lieu of the jets 1000 and 1002.

In a toy, lecture demonstrating device, etc., the jets 1000 and 1002 may be turned by hand instead of by motors, etc. Sufficient frictional resistance may be provided for such manually adjustable jets so they tend to remain in the selected adjusted position until again manually adjusted. In such case handles similar to switch handles 1005 and 1007 may be provided to simulate or illustrate the electrical power control of the jets 1000 and 1002.

In a machine for carrying passengers, in the embodiment of FIGS. 50—54, the length of the vehicle may be 14 feet and the width 8 feet. The height of the side wall 900 may be 32 inches. In a toy, or amusement device, or educational device of the embodiment of FIGS. 50—54, inclusive, the length may be 20 inches and the width 12½ inches. The side wall 900 may be 8 inches high, and the curtain height may be 5 inches, exclusive of the rings 914 to 928, inclusive. The large scale passenger model may have corresponding curtain heights, etc. In the passenger model the outer diameter of the outer curtains 908 and 906 may be 5 feet, while the diameter of the inner curtains 907 and 909 may be 4 feet. The smaller model may have curtains of corresponding size. The height of the rings 914 to 928 inclusive may be varied from zero to any desired height, such as in the proportion to the height of wall 900 shown in the drawings.

The rings 914 and 918, and the rings 916 and 920 may be supported from the floor 904, which is cantilevered by the side and end walls of box 939. The outer edges of the rings 924 and 928 may be supported by bars 1004, which bars straddle the openings for the curtains. The ends of these bars 1004 rest on the upper surface of the floor 904. The bars 1004 may be made slightly thicker where they are attached to the rings 924 and 928.

If desired, the tops of the upper surface of floor 904 in sub-plenum chambers 974, 976, 984 and 986 may be coated with a

slightly abrasive paint, as shown in FIGS. 50 and 53. This paint may be omitted, if desired.

The blowers 956 and 958 may be driven by the engines 1010 and 1012. These engines may be internal combustion engines of the horizontal shaft type which are provided with drive pulleys 1014, which drive the driven pulleys 1016 by drive belts 1018. If desired, the internal combustion engines 1010, 1012 may be provided with air intake and combustion gas exhaust passageways 1020 and 1022 respectively. The engine 1010 may be under the seat 1024.

In the embodiment of FIGS. 50 through 54, the vehicle, toy, etc., may stand in idle position on pedestals, runners, wheel supports, etc., as indicated by the dotted lines 1030, which may be similar to the supports 690 of FIGS. 35 and 36, 76, 76J of FIGS. 1, 3 and 5, and 380 of FIGS. 21 through 24, etc. The passengers, cargo, etc., may be positioned on the vehicle at proper compartments, and the engine or engines or motors 1010 and 1012 may be started by suitable energizing means, such as ignition and cranking means or turning on of electrical power for motors, so that the blowers 956 and 958 are actuated. At this time jets 1000 and 1002 may be at idle positions 1000C and 1002C. The blowers deliver air under superatmospheric pressure into the sub-plenum chambers 974, 976, 984, and 986, through the openings or exhausts 970, 972, 980 and 982. Such superatmospheric air is then delivered through openings 906—908 in the floor 904 and through rings 914, 916, 918, 920, 922, 924, 926, and 928, into the four curtain air spaces 934 and 936 to inflate the respective four curtains and to cause them to produce a lifting action of the vehicle, toy, educational demonstrator, etc., by air cushion actions, substantially identical with the air cushion lifting actions described in connection with all of the other curtain embodiments disclosed herein. The superatmospheric air from the air cushions is discharged through the small annular spaces between the ring-shaped channels 930 and the ground surface 932, also substantially as described elsewhere in connection with the other embodiments. Such vehicle, toy, educational demonstrator, etc., if provided with the jets 1000 and 1002, may be caused to move forward, sidewise, backward, or to stop or idle by properly positioning the jets 1000 and 1002 to desired proper positions such as 1000A through 1000F, and 1002A through 1002F, as previously described. If not provided with such jets, the embodiment may be pulled or pushed about for transportation of cargo, passengers, etc., or for amusement and/or educational purposes, as desired.

In the embodiment of FIGS. 1 through 5, for example, as well as in corresponding elements in all other embodiments, the flow of superatmospheric air into the annular curtain space 38 and into the central core space 34 should be guided by baffle action, blower action, etc. to maintain a proper relative pressure in the spaces 38 and 34 to maintain the curtain walls 62 and 68 in down position, during operation, as shown in FIG. 2, with the aid of the Venturi action at 56. The same relationship of pressures should be maintained in all other embodiments herein disclosed.

Where applicable any feature of any embodiment may be applied to any other embodiment, as desired.

The curtain material, shape, mode of operation, etc., may be substantially the same or similar in all of the embodiments herein disclosed.

It is thus to be seen that a lifting device or combination has been provided which is supported slightly above a "ground" surface by an air cushion, or a plurality of air cushions, having superatmospheric air pressure during normal operation. Such one or more air cushions are each surrounded by a flexible, hollow, columnar curtain which is shaped to maintain itself in load-supporting condition during normal operation. The curtain is so constructed that it yieldingly glides over relatively high objects and requires very small power consumption to maintain the craft in operation. A new lifting method is produced thereby.

Grilles and the like may be used to guard the exposed moving parts. Such grilles may be of the type which prevent inser-

tion of the hands, etc., but permit easy flow of air. For example, the exposed blower parts at any of the air intakes may be protected by such a grille, not shown, to prevent injury or accidental entrance of harmful objects, etc.

While the form of the invention now preferred has been disclosed, as required by statute, other forms may be used, all coming within the scope of the claims which follow.

I claim:

1. A ground proximity fluid cushion supporting device comprising, a platform, a flexible diaphragm underlying said platform shaped to provide a perimetrical depending convolution, the periphery of said diaphragm being hermetically attached to said platform and the central portion thereof being restrained in a fixed position beneath said platform above the lower most extremity of said convolution thereby forming a plenum cavity between said diaphragm and the ground and an annular cavity between said diaphragm and said platform, means formed inboard of said convolution providing direct communication between said annular cavity and said plenum cavity, and means for introducing fluid under pressure directly into one of said cavities.

2. The device set forth in claim 1 wherein the means for introducing fluid under pressure directly into one of the cavities comprises conduit means in fluid communication with said one of the cavities and a means for supplying fluid under pressure.

3. A lifting device having in combination a plenum chamber formed by an upper horizontal panel and an enclosing side wall construction extending downwardly from said panel; a blower supported on said plenum chamber and having an air inlet connected with the surrounding atmosphere and connected to an air outlet which discharges air at superatmospheric pressure into said plenum chamber; and a flexible hollow columnar, double walled curtain suspended at its upper edges from and sealed at its outer upper edge to said plenum chamber and restraining a portion of an air cushion at superatmospheric pressure formed under said panel, said curtain having two flexible walls spaced apart at the upper edges of said curtain and joined together at the lower edge of said curtain and restraining part of said air cushion between said flexible walls at relatively high air pressure and having its lower edge slightly spaced from a "ground" surface under normal operation for restrained escape of air from said cushion between said lower edge of said curtain and said ground surface at relatively low air pressure to cause a downward pull on said air curtain.

4. A combination to be supported slightly above a "ground" surface by an air cushion having a superatmospheric air pressure during normal operation comprising: a supporting member; air introducing means discharging air at superatmospheric pressure into said air cushion; and a flexible, hollow columnar curtain sealed to and suspended at its upper edge from said supporting member, surrounding at least the lower part of said air cushion, and having its lower edge slightly spaced from said "ground" surface during normal operation for restrained escape of air from said air cushion between said lower edge and said "ground" surface, said lower edge of said curtain including means responsive to downward relatively low air velocity and high air pressure of said air cushion, and to relatively high velocity low air pressure between said lower edge and said "ground" surface to urge said lower edge of said curtain toward said "ground" surface.

5. A combination to be supported slightly above a "ground" surface by an air cushion having a superatmospheric air pressure during normal operation comprising: a supporting member; air moving means having air intake means connected with the surrounding atmosphere and discharging air from said surrounding atmosphere at superatmospheric pressure into said air cushion; a flexible, hollow columnar curtain sealed to and suspended at its upper edge from said supporting member, surrounding at least the lower part of said air cushion, and having its lower edge slightly spaced from said

"ground" surface during normal operation for restrained escape of air from said air cushion between said lower edge and said "ground" surface, said curtain having an outer substantially vertical wall during normal operation with a continuous inward sidewise extension at its lower edge to produce a relatively slow moving high air pressure above said extension and a relatively high velocity low air pressure below said extension to produce a downward pull at the lower edge of said curtain.

10 6. A combination to be supported slightly above a "ground" surface by an air cushion having a superatmospheric air pressure during normal operation comprising: a supporting member; air moving means having air intake means connected with the surrounding atmosphere and discharging air from said surrounding atmosphere at superatmospheric pressure into said air cushion; a flexible, hollow columnar double wall curtain suspended at its upper edges from and sealed at its outer upper edge to said supporting member, surrounding at least the lower part of said air cushion, and having its lower edge slightly spaced from said "ground" surface during normal operation for restrained escape of air from said air cushion between said lower edge and said "ground" surface, said curtain having an outer wall joined at its lower edge to an inner wall which extends upwardly and inwardly from the lower edge of said outer wall into said air cushion to form a low velocity high pressure air body between said outer and inner walls and a high velocity low pressure air stream below said walls.

15 7. A combination to be supported slightly above a "ground" surface by an air cushion having a superatmospheric air pressure during normal operation comprising: a supporting member; air moving means supported by said supporting member and having air intake means connected with the surrounding atmosphere and discharging air from said surrounding atmosphere at superatmospheric pressure into said air cushion; a flexible, hollow columnar double wall curtain suspended at its upper edges from and sealed at its outer upper edge to said supporting member, surrounding at least the lower part of said air cushion, and having its lower edge slightly spaced from said "ground" surface during normal operation for restrained escape of air from said air cushion between said lower edge and said "ground" surface, and movable weight means to produce a controlling force in said combination.

20 8. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

25 9. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication between said air cushion and said columnar band defined by said inner and outer walls; and air introducing means for introducing air into said air cushion at superatmospheric pressure for support of said supporting member during normal operation.

30 10. An apparatus for lifting a load which comprises: a supporting member to receive said load; a curtain to surround a cushion of air at relatively low superatmospheric pressure between a "ground" surface and said supporting member, said curtain having a cylindraceous wall secured to said supporting member and extending downwardly to a lower edge forming a relatively narrow space above said "ground" surface, said cylindraceous curtain wall being made of thin, flexible, air impermeable, relatively nonstretchable material which is so thin relatively to its width it is relatively non-self-supporting in an

35 11. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

40 12. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, and movable weight means to produce a controlling force in said combination.

45 13. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

50 14. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

55 15. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

60 16. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

65 17. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

70 18. A combination to be supported slightly above a "ground" surface by an air cushion having a superatmospheric air pressure during normal operation comprising: a supporting member; a flexible columnar curtain suspended from said supporting member, said curtain having an outer wall and an inner wall merged together, said curtain having a lower edge slightly spaced from said "ground" surface during normal operation for restrained escape of air from said air cushion between said lower edge and said "ground" surface, said outer wall and said inner wall encompassing a columnar band filled with air from said air cushion at superatmospheric pressure, which columnar band surrounds at least a part of said air cushion and said inner wall having its upper edge spaced from said supporting member so as to permit free communication

edgewise direction of air from said air cushion through said narrow space below said lower edge at a lower superatmospheric pressure than the pressure of said cushion of air to cause a downward pull on said lower edge of said cylindraceous curtain wall; and means for introducing air at relatively low superatmospheric pressure into said cushion of air to cause air to discharge from said cushion of air through said narrow space below the lower edge of said cylindraceous wall at a lower superatmospheric air pressure than the pressure of said cushion of air.

10. An apparatus according to claim 9 in which said relatively low superatmospheric air pressure in said air cushion is in the order of a fraction of an ounce per square inch higher than the air pressure of the atmosphere adjacent the outer surface of said apparatus.

11. An apparatus according to claim 9 in which said means included at the lower edge of said curtain to cause a downward pull on said lower edge comprises an inward extension on said lower edge of said cylindraceous wall.

12. A lifting device comprising: a supporting member; a flexible, open bottom, columnar curtain, sealed to and depending from said supporting member, said curtain being made of thin, flexible, air impermeable, relatively non-stretchable material which is relatively non-self-supporting in an edgewise direction; air introducing means to introduce air at superatmospheric pressure into said curtain to produce an air cushion to lift said supporting member and to lift the lower edge of said curtain to produce a relatively narrow circumferential space under said lower edge and a "ground" surface under said curtain; and downward pulling means at said lower edge adjacent the lower edge of said curtain responsive to downward relatively low air velocity and high air pressure of said air cushion and to relatively high velocity low air pressure between said lower edge and said ground surface.

13. A lifting device comprising: a relatively rigid supporting member with a peripheral orbital support for a curtain; an orbital, flexible, channel shaped, sheet curtain with an outer edge secured to said peripheral orbital support and with an inner edge secured to a support inside the vertical bounds established by said peripheral orbital support and under said rigid supporting member, said curtain having an intermediate low periphery between said inner and outer edges of said curtain and there being a peripheral air space between said curtain edges, and there being a core air space inside said inner edge; said peripheral air space and said core air space being connected for interchange of air, and superatmospheric pressure air supply means to introduce superatmospheric air into an air cushion below said supporting member surrounded by said curtain to lift said supporting member with said intermediate low periphery of said curtain spaced slightly above a "ground" surface under said lifting device.

14. A lifting device comprising: a composite plenum chamber having relatively rigid upper and lower substantially horizontal members and a vertically directed peripheral wall connected to and sealing said horizontal members into a plenum chamber, said lower substantially horizontal member having a plurality of openings and vertically directed baffles between said horizontal members and between said openings substantially isolating spaces above said openings into isolated sub-plenum chambers; a plurality of flexible, laterally spaced apart, open bottom and open top downwardly directed curtains with upper edges sealed to said lower horizontal member and surrounding a respective one of said openings to be connected to a respective sub-plenum chamber to form a plurality of air cushions surrounded by a respective curtain, said cushions extending from a respective sub-plenum chamber and a "ground" surface with the lower edges of said curtains spaced a narrow peripheral distance from said ground surface and means to introduce air under pressure into said sub-plenum chambers.

15. A lifting device comprising: a relatively rigid supporting member with a plurality of peripheral orbital supports; a plurality of orbital, flexible, channel shaped, laterally spaced

apart sheet curtains with their respective outer edges secured respectively to each of said peripheral orbital supports and with their respective inner edges secured to respective supports inside the vertical bounds established by said respective

5 peripheral supports and under said rigid supporting member, said curtains having respective intermediate low peripheries respectively between said inner and outer edges and there being a respective peripheral air space between the respective curtain edges and there being a respective core air space inside the respective inner edges; and superatmospheric pressure air supply means to introduce superatmospheric air into said air spaces to form respective air cushions below said supporting member to lift said supporting member with said intermediate low peripheries of said curtains spaced slightly above a "ground" surface under said lifting device.

16. A lifting device according to claim 15 in which said air supply means supplies superatmospheric air substantially independently into the peripheral air spaces and core air spaces of each respective air curtain.

20 17. A lifting device according to claim 15 in which propulsion and guiding means are provided.

18. A lifting device according to claim 15 in which air flow, adjustable, propulsion and guiding means are provided.

25 19. A ground effect vehicle comprising a horizontal support frame and at least three separate, noncommunicating plenum chambers extending downwardly therefrom, a ducted fan arranged for discharging into at least two of said chambers, guide means defining at least two separate, nonintercommunicating flow passages from the immediate vicinity of the discharge side of said fan and into respective ones of said two plenum chambers.

20 20. A lifting device comprising: a supporting member; a plurality of flexible, orbital band shaped, laterally spaced apart, 35 open bottom, downwardly directed curtains sealed to and depending from said supporting member, each of said curtains being made of thin, flexible, air impermeable, relatively non-stretchable material; air introducing means to introduce air at superatmospheric pressure within each of said curtains to produce substantially independent air cushions surrounded in part by each respective curtain to lift said supporting member and to lift the respective lower edges of said respective curtains a relatively narrow peripheral distance above a "ground" surface under said curtains; and downward pulling means 40 the lower edges of said respective curtains responsive to air at relatively low superatmospheric pressure in said air cushions and the discharge of air from said air cushions through the narrow space below said lower edges at a lower superatmospheric pressure than the pressure of said cushions of air to produce a downward pull on each of said curtains.

21. A lifting device according to claim 20 in which the supporting member includes a relatively rigid platform for supporting said curtains.

55 22. A lifting device according to claim 20 in which there are three of said curtains supported by said supporting device with their axes in tripod relationship.

23. A lifting device according to claim 20 in which directional control means are provided.

60 24. A lifting device according to claim 20 in which air flow reaction directional control means are provided.

25. A lifting device according to claim 20 in which means are provided to introduce air at superatmospheric pressure substantially independently into the air cushions within each 65 of said curtains.

26. In a method for sustaining on a fluid cushion above a "ground" surface a device having a platform means and a flexible diaphragm sealed at its upper edge to said platform means and extending downwardly therefrom to a lower edge having an inwardly extending portion and adapted to define a relatively narrow space above said ground surface, the steps comprising:

introducing fluid at relatively low superatmospheric pressure within said diaphragm and intermediate said platform means and said ground surface to provide a fluid

cushion at relatively low superatmospheric pressure therebetween and cause said lower edge of said diaphragm to define a narrow space above said "ground" surface; and permitting a restrained flow of fluid from said fluid cushion through said narrow space at a lower superatmospheric pressure than that of said fluid cushion so that said lower edge of said diaphragm will be urged toward said ground surface by the higher fluid pressure of said fluid cushion acting on said inwardly extending portion of said lower edge of said diaphragm to thereby maintain its narrow spacing therefrom and the restrained flow of fluid from said fluid cushion therethrough.

27. In a method for sustaining above a "ground" surface an air supported device having a platform means; a plurality of laterally spaced apart curtains each of which have a substantially straight vertical columnar wall formed of thin flexible, air impermeable material secured at its upper edge to said platform means and extending downwardly to a lower edge

forming a relatively narrow space above said ground surface and having an inward extension at said lower edge the steps of: introducing air at relatively low superatmospheric pressure into each of said curtains to provide cushions of air therewithin; and discharging air from said fluid cushions through each of said relatively narrow spaces and below each of said inward extensions at a lower superatmospheric air pressure than that of said air cushions to thereby urge each of the lower edges of said columnar walls downwardly toward said "ground" surface by means of the higher air pressure of said air cushion on the upper side of said inward extensions.

28. A method according to claim 27 in which said relatively low superatmospheric air pressure of each of said air cushions is in the order of a fraction of an ounce per square inch higher than the air pressure of the atmosphere adjacent the outer surface of said cylindraceous curtain walls.

UNITED STATES PATENT AND TRADEMARK OFFICE
CERTIFICATE OF CORRECTION

PATENT NO. : 3,532,179

DATED : October 6, 1970

INVENTOR(S) : Norman Bryan McCreary

It is certified that error appears in the above-identified patent and that said Letters Patent is hereby corrected as shown below:

Claim 9:

Column 35, line 1, after "direction" and before "of" insert:

--and said lower edge of said curtain including means responsive to air at relatively low super-atmospheric pressure in said air cushion and the discharge--

Signed and Sealed this
Nineteenth Day of March, 1991
